UNITED STATES PATENT OFFICE.

HERBERT E. ENSLIN, OF MALDEN, MASSACHUSETTS, ASSIGNOR TO UNITED SHOE MACHINERY COMPANY, OF PATERSON, NEW JERSEY, A CORPORATION OF NEW JERSEY.

BUTTONING-MACHINE.

1,207,151.

Specification of Letters Patent.

Patented Dec. 5, 1916.

Application filed September 12, 1912. Serial No. 719,979.

To all whom it may concern:

Be it known that I, HERBERT E. ENSLIN, a citizen of the United States, residing at Malden, in the county of Middlesex and 5 State of Massachusetts, have invented certain Improvements in Buttoning-Machines, of which the following description, in connection with the accompanying drawings, is a specification, like reference characters on 10 the drawings indicating like parts in the several figures.

This invention relates to buttoning machines and the machine herein shown and described for the purpose of illustrating one 15 embodiment of the invention is particularly designed for operating upon the uppers of boots and shoes.

Viewed in its broad aspects, the general object of the invention is to provide a buttoning machine by the use of which buttoning operations may be performed quickly 20 and satisfactorily and without danger of damaging the work operated upon.

More particularly, the invention aims to 25 provide a satisfactory machine especially adapted for use in buttoning the uppers of boots and shoes.

In the manufacture of button boots and shoes, it is the general practice, after the 30 different parts of an upper and its lining have been stitched together and preparatory to the assembling and lasting operations, to button a sufficient number of the lower buttons upon the upper to hold the button 35 piece and the buttonhole fly correctly positioned with relation to each other to permit the upper to be fitted properly to the last and the shoe to be lasted properly. This operation of partially buttoning the uppers 40 of button boots and shoes preparatory to the assembling and lasting operations has heretofore been performed in shoe factories by hand operatives employing ordinary button hooks. Hand buttoning is, however, open 45 to serious objections. The hand method is expensive because the operation of buttoning each button is somewhat complicated and, more particularly, because the buttoning must be done one button at a time, so that 50 for both these reasons the output by the hand method is necessarily small. Moreover, this hand operation requires considerable skill and, in consequence, hand operatives receive comparatively high wages considering their output. The hand method is

also expensive because of frequent damage done to the work, for example by stretching or tearing out buttonholes or by ripping off buttons.

No practicable machine for performing 60 the above mentioned buttoning operation has heretofore been proposed and in shoe factories, prior to this invention, so far as I am aware, this operation has been performed universally by hand. 65

Since, as above suggested, it is commonly desired in buttoning the uppers of boots and shoes to button a plurality of buttons upon each upper, usually at least three or four and frequently seven buttons, the preferred 70 embodiment of the invention is designed to permit the presentation thereto of work provided with a plurality of buttons and buttonholes and to perform substantially simultaneously as many complete buttoning operations as may be desired with respect to the 75 said work. Preferably, too, the machine will be constructed and arranged to be substantially entirely automatic in its operation after the work has been introduced into the 80 machine so that the operator, after placing the work in the machine, can take up and arrange another piece of work in readiness to introduce that into the machine as soon as the first piece of work is discharged therefrom. 85

Very important features of the invention reside also in the shapes of the various devices employed and in the combinations and organizations through which those devices 90 are operated in proper time relation to cause the various steps in the operation of the machine and the operation of the machine as a whole to be performed effectively and rapidly. 95

These and other objects and features of the present invention, including numerous novel details of construction and combinations of parts, will appear from the following detailed description read in connection 100 with the accompanying drawings and the novel features of the invention will then be defined in the appended claims. It is to be understood however that, although in the foregoing statement of the objects of the invention, and in the following description 105 emphasis is placed upon certain particular objects and features of the invention, the invention is not intended to be limited thereby. 110

It is also to be understood that, although the preferred embodiment of the invention is herein described as being especially designed for use in the manufacture of boots and shoes and particularly for use in partially buttoning shoe uppers prior to the assembling and lasting operations, it is nevertheless contemplated that, as above suggested, the present invention as a whole or various features thereof may have many and widely different applications. Accordingly, the scope of the invention is to be determined by the broadest construction of the terms of the claims which is permitted by the prior art.

Referring to the drawings:—Figure 1 is a side elevation of a machine embodying the present invention; Fig. 2 is a front elevation of the machine; Fig. 3 is a central longitudinal vertical section; Fig. 4 is an angular perspective of a portion of the machine as viewed from the front, showing the various operating instrumentalities of the machine in their initial positions; Fig. 5 is an isometric perspective, looking toward the front of the machine from a point above and at the rear of the center of the machine, various interfering parts of the frame and operating mechanisms having been broken away; Fig. 6 is a side elevation showing the relative locations of the various operating instrumentalities of the center set in the initial positions of the parts; Fig. 7 is a detail in perspective of parts shown in Fig. 5 in the same positions of the parts; Figs. 8, 10, 12, 13 and 15 are views similar to Fig. 6 with the parts in successive selected positions; Figs. 9, 11, 14 and 16 are details similar to Fig. 7 with the parts in positions corresponding to the respective positions of the parts shown in Figs. 8, 10, 13 and 15; Fig. 17 is a detail in side elevation illustrating the positions of a buttoner and of the work holding means with relation to the work at the conclusion of a buttoning operation; Fig. 18 is a front end detail, partly in section, with the parts in the positions shown in Fig. 17 and on a somewhat larger scale; Fig. 19 is a side elevation illustrating the operation of the means for discharging the buttoned work from the machine; Fig. 20 is an angular perspective looking from above of a part of the work receiving means; Fig. 21 is a vertical section of a part of the means for holding a button and positioning a buttonhole for a buttoning operation; Figs. 22 and 23 are details in perspective of parts shown in Fig. 21; Fig. 24 is a detail in perspective of the lower portion of one of the buttoning instrumentalities, and Fig. 25 is an exploded view in detail of a button holder.

The machine frame 2, which supports the operating parts of the machine, is designed to be placed upon a suitable work bench or

table. The frame 2 is provided with a cover 4 (Fig. 1) pivoted at 6 to the said frame to permit the cover to be swung backwardly to afford access to the parts housed within the frame. Conveniently, the cover 4 is provided with a window (not shown), the location of which is indicated generally at 8 to let light through to the work.

Mounted in suitable bearings in the frame 2 is a driving shaft 10 (Figs. 1 and 2) which carries fixed thereto a driving pulley 12. Secured to the hub of the driving pulley 12 is a pinion 14 meshing with a spur gear 16 loose on a counter shaft 18 (Fig. 3) which carries the cams from which the principal moving parts of the machine are operated, the direction of rotation of the shaft 18 being indicated by the arrow (Fig. 1).

The clutch for causing the cam shaft 18 to be driven from the driving shaft 10 through the pinion 14 and spur gear 16 may be of any suitable construction, the illustrated machine being provided with one form of the well known "Horton" clutch having a stop 20 (Fig. 1) controlled by a detent 22 slidably mounted on a rod 24 and normally pressed downwardly by a spring 26. The rod 24 which carries the detent 22 is secured to one arm 28 of a bell crank lever indicated generally at 30 and fulcrumed on the machine frame at 32, the other arm 34 of the bell crank lever 30 being operated by a detent 36 (Figs. 1 and 2) on an arm 38 linked to a treadle rod 40 passing through a split end of the lever arm 34 and a slot 42 in the machine frame and connected at its lower end to a starting treadle not shown.

Upon depressing the starting treadle, the detent 36 is forced downwardly into engagement with a projecting plate 44 connecting the branches of the split end of the lever arm 34 of the bell crank lever 30, with the result that the arm 34 is swung downwardly and the detent 22 is disengaged from the stop 20, thereby throwing in the clutch and starting the machine. The clutch is constructed to maintain a driving connection between the cam shaft 18 and the driving shaft 10 during one complete revolution of the cam shaft 18 at the end of which the clutch is thrown out. To cause the clutch to be thrown out automatically at the end of one complete revolution of the cam shaft 18, the cam shaft 18 has fixed thereto a cam 46 (Fig. 1) having a high point 48 adapted at the end of one-half a revolution of the cam shaft 18 to engage and raise one arm 50 of a lever, indicated generally at 52 and fulcrumed on the driving shaft 10, of which lever the other arm 54 (Figs. 1 and 2) carries at its free end a pin 56 which is caused by upward movement of the lever arm 50 to engage and throw the arm 38 sidewise to disengage the detent 36 from the projection 44 on the lever arm 34, whereupon the arm 38

34, being released by the detent 36, rises under the influence of a spring 58, pinned at one end to the arm 34 and at its other end to the machine frame, and the detent 22 5 is thereby thrown into position to engage the stop 20 and throw out the clutch to stop the machine. A spring 60, connected at its lower end to a pin 61 on the arm 38 and at its upper end by a pin 63' to the machine 10 frame, normally tends to pull the arm 38 and treadle rod 40 upwardly to restore the treadle to its initial position when released by the operator.

As heretofore suggested, the machine is 15 designed to be capable of performing at substantially the same time a plurality of buttoning operations, the operation of completely buttoning a single button being usually herein termed a buttoning operation. For operating on each button, the 20 illustrated machine has a set of operating instrumentalities comprising work receiving means and buttoning means. As shown, the machine has seven such sets of operating 25 instrumentalities, although obviously the number of sets may be greater or less as desired, the illustrated machine being equipped with the above stated number of sets because in practice seven buttons is usually 30 the greatest number which it is desired to button with respect to a single upper.

The work receiving means include both button holders and buttonhole fly holders, usually herein termed fly holders. For receiving the buttons, each set is provided with a button holder comprising an upper U-shaped horizontally disposed fork 62 having an extended shank 63 superimposed upon and secured as by screws 64 (Fig. 3) 35 to a block 66, a lower fork 68 carried at the front end of the block 66 and a pair of fingers 70 below the fork 68 and pivoted by pins 69 to a plate 71 (Figs. 6 and 25). Springs 73, by engagement with the outer 40 sides of the fingers 70, cause the said fingers to be normally held together. The pins 69 pivotally secure the fingers 70 between the block 66 and the plate 71 (Fig. 25), passing through holes 75 in the rear ends of the 45 spring-pressed fingers 70 and through holes 77 in the plate 71, while the plate 71 is secured to the under side of the block 66 by a screw 79 passing through plate 71 at 81. The springs 73 are connected by an integral 50 bar 83 received in a slot 85 in the under side of the shank 63 of the fork 62 and secured in place between the shank 63 of the fork 62 and the block 66 by one of the screws 64 passing through the bar 83 at 87 into the 55 said shank 63 at 89. The forks 68 are designed to sustain the heads of the buttons while the spring fingers 70 are arranged to receive the eyes of the buttons between them. The forks 68 also constitute guides to facilitate the introduction of the button eyes be-

tween the spring fingers 70 and, with this in view, are preferably arranged to project forwardly at their ends slightly beyond the forward ends of the spring fingers 70. Preferably, too, the forks 68 are formed with 70 their prongs somewhat blunt to prevent the said prongs catching in the work during the placing of the buttons in the button holders and, particularly, to prevent the said prongs from picking up and catching in the line of 75 button fastening thread on the inside of the button piece.

In order that the spring fingers 70 may embrace and inclose snugly with yielding pressure the eyes of buttons thrust between 80 the said fingers, the fingers of each pair have their inside faces notched near their front ends as best shown in Fig. 25. In the use of the above described button receiving means, the buttons are held upright in the 85 holders by reason of the flat bottoms of the button heads resting squarely upon the upper faces of the forks 68, while the spring fingers 70 by closely embracing the eyes of the buttons prevent accidental disengagement of the buttons from the forks 68 and the upper forks 62 limit movement of the buttons transversely of the button holders by engagement with the peripheries of the 90 button heads on opposite sides thereof. 95

Each of the blocks 66, which carry the button guides 68, is set into a slide bar 72; the slide bars 72, as shown, being so cut away to receive the blocks 66 that the upper faces of the blocks 66 and the adjacent upper faces of the slide bars 72 are in the same horizontal plane. The slide bars 72 are each supported in a guide 74 (Fig. 5), the guides 74 being secured against movement lengthwise of the machine by interlocking engagement of upstanding projections 76 from each of the said guides 74 with shoulders 78 formed by slots 80 in a tie plate 82 (Figs. 2 and 5) extending transversely of the machine and secured at either end as by bolts 100 105 84 (Fig. 5) to ledges 86 on the inside faces of the side walls of the machine frame 2.

For receiving the buttonhole fly, each set includes a fly holder comprising a horizontally disposed fork 88, positioned above and 110 in vertical alignment with the corresponding button holder, and a buttonhole spreader to be hereinafter described. Each fly supporting fork 88 is formed on the front end of a slide bar 90. The slide bars 90 pass 115 through and are supported in the guides 74, each slide bar 90 being superimposed and resting upon the corresponding slide bar 72 of the series of slide bars which carry the 120 button holders.

At their rear ends, the slide bar 90 and the slide bar 72 of each set are split and the split ends of the said slide bars are respectively adjustably secured, as by set screws 92 and 94 (Figs. 3 and 5), in open shells 130 125 96

and 98 placed back to back, the said screws 92 which secure the rear ends of the slide bars 90 passing through a slot 100 in a frame 102 mounted for sliding movement lengthwise of the machine on ways 104 on the opposed inner faces of the side walls of the frame 2, and the said screws 94 which secure the rear ends of the slide bars 72 being similarly arranged in a slot in a frame 106 mounted in the same manner to slide along ways 108 on the machine frame. Movement of the frame 102 one way or the other lengthwise of the machine operates to reciprocate the forks 88 in and out toward and from the machine, while movement of the frame 106 one way or the other operates similarly to move the button holders in and out toward and from the machine, the movements of the fly holder forks 88 and button holders backwardly toward the machine being for the purpose of carrying the work into position to be delivered to the buttoning means and thereafter withdrawing them to inoperative position and the opposite movements of the fly holders and button holders forwardly away from the machine serving to restore them to their initial work receiving positions. For thus operating the frames 102, 106, which, as above stated, move the slide bars 90 and 72 and, consequently, the fly holders and button holders lengthwise of the machine, the frame 106 has a rearward extension 110 (Figs. 3 and 5) pivotally connected to a link 112 pivoted to one arm 114 of a bell crank lever indicated generally at 116 (Fig. 3) and fulcrumed on the machine frame, the lever 116 carrying at the end of its other arm 118 a cam roll 120 traveling in a cam path 122 on the inside face of a cam 124 on the cam shaft 18. For similarly operating the frame 102, the said frame has a rearward extension 126 connected in the same fashion by a link 128 to an arm 129 of a bell crank lever indicated generally at 130 and fulcrumed on the machine frame, the lever 130 carrying at the end of its other arm 131 a cam roll 132 engaging a cam path 134 on the inner face of a cam adjacent to the cam 124 on the cam shaft 118.

The buttonhole spreaders which, with the forks 88, constitute the fly holders, comprise for each set a pair of horizontally disposed spreader arms 136 located below the fly supporting forks 88 and pivoted at their rear ends for opening and closing movement in a U-shaped shell 138 at 139 (Fig. 20). In order that the spreaders may be moved with the forks 88 lengthwise of the machine upon movement of the slide bars 90, each shell 138 is connected at 140 to the corresponding fly holder slide bar 90 near the front end of the said slide bar 90, the slide bars 90 being each cut away as indicated, for example, in Fig. 6, to accommodate the shells 138. Each

spreader arm 136 carries on its front end an upstanding blade like projection 142. The two spreader blades 142 of each set in their initial and normal position project upwardly through the corresponding fork 88, as shown for example in Fig. 6. To maintain the spreader arms 136 of each set normally together in their closed position, extensions of opposite sides of each of the shells 138 constitute spring fingers 144 (Figs. 6 and 20) which press inwardly against the outer faces of each pair of spreader arms 136.

In the use of the machine, the buttonhole fly, indicated at A in various figures, is initially positioned, as shown for example in Figs. 3, 4, 6 and 7, the buttonhole fly A being rested upon the supporting forks 88 and the spreader blades 142 projecting upwardly through the buttonholes.

In view of the fact that the buttonhole fly frequently exhibits a tendency to buckle and round up toward the center, the forks 88 preferably, as shown in Figs. 1, 2 and 4, have their fly supporting faces disposed at elevations progressively increasing from the end members toward the center of the series, the forks 88 in the illustrated construction progressively increasing in thickness toward the center. To prevent catching in the outer or end buttonholes of the series of buttonholes to be operated upon during the introduction of the work into the fly holders, each of the outer forks 88 preferably has only one prong, as best shown in Fig. 4, this prong being disposed inside of the adjacent spreader blades 142, the outer members 88 being nevertheless for convenience generally herein referred to as forks as well as the intermediate and forked members 88. In the illustrated construction, too, the spreader blades 142 progressively increase in height so that each pair of blades 142 may have substantially the same relative position with respect to the adjacent fork 88. Preferably also the outside pairs of spreader blades 142 are bent slightly outwardly as best shown in Fig. 4, to obviate the danger of the fly springing away from the forks 88 after the operator has positioned the fly thereon and released it.

In their initial positions, the button and fly holders are, for convenience in introducing the work, projected forwardly away from the machine and in front of the buttoning means (see, for example, Fig. 3), the term "work" as employed in this specification and the appended claims being, for convenience, used in a broad sense to designate whatever is handled or operated upon by the various instrumentalities of the machine or any of them, and being therefore variously applied for example to the upper as a whole, to the button-piece or buttonhole fly or both or to the buttons attached to the

upper. It will also be noted that to facilitate further the introduction of the work, the several button and fly holder forks each open outwardly away from the machine and 5 toward the operator. During the first part of the operation of the machine, the fly holders through their above-described operating mechanism are moved backwardly toward the machine to position the buttonholes for the action of the buttoning means (Fig. 8), the spreader blades 142 preventing accidental disengagement of the fly from the fly holders during movement thereof, and thereafter the button holders are similarly 10 moved backwardly into the position shown in Fig. 12 to bring the buttons into alignment with the buttonholes and in position for the operation of the buttoning means. During the backward movement of the fly 15 holders relatively to the button holders, the spreader arms 136 are forced apart to cause the spreader blades 142 to act on opposite sides of each of the buttonholes to spread the buttonholes and hold them open (Fig. 9) 20 to facilitate the entrance therein of the button head engaging means, as will be herein-after more fully explained. In order to cause the spreader arms to be thus separated during the above mentioned backward movement of the fly holders, each of the shanks 63 of the forks 62 of the button holders has upstanding therefrom a projection 146 (Figs. 6 and 20) standing, in the normal 25 position of the parts, in a slot formed by recesses or notches in the adjacent faces of the corresponding spreader arms 136 so that the projections 146, during a part of the operation of the machine, are in sliding engagement with the inner faces of the 30 spreader arms 136 with the result that, upon backward movement of the fly holder forks 88 while the button holders remain stationary, the spreader arms 136 will be wedged apart as soon as the openings between the 35 said spreader arms are carried beyond the projections 146 and the spreader blades 142 of each pair will be oppositely moved to open the buttonholes, the relative positions of the above mentioned parts at this point 40 in the operation of the machine being shown in Figs. 8 and 9. For the purpose of permitting the spreaders to be later lowered to withdraw them from the buttonholes, the connections 140 of the shells 138 with the 45 fly holders 90 are pivotal connections about which the shells 138 may swing downwardly and upwardly. For lowering the spreaders out of the buttonholes and withdrawing them backwardly into an inoperative position 50 after the buttonholes have been presented to the buttoning means and thereby engaged and held for the buttoning operations, the shells 138 which carry the spreader arms 136 are provided with rearward extensions 148 (see, for example, Figs. 6 and 55 20), having curved end faces 150 adapted to slide over inclined faces 152 formed on the blocks 66 which carry the button guides 70. The construction is such that, at the proper time, backward movement of the slide bars 70 90 which carry the fly supporting forks 88, while the slide bars 72 which carry the button holders remain stationary, will cause the curved end faces 150 on the shells 138 to ride up over the inclined faces 152 on the 75 blocks 66, thus tipping the shells 138 about their pivots 140 in a direction to swing the spreader arms 136 downwardly to withdraw the spreaders from the buttonholes, continued backward movement of the fly holder 80 slide bars 90 then operating to carry the spreaders backwardly to an inoperative position shown in Fig. 10. In order to provide that the spreaders may be held normally in their uppermost position, the shells 138 and 85 the shanks 63 of the forks 62 are provided with opposed coöperating abutments 153 and 155 and each of the fly holder slide bars 90 is provided with a spring pressed plunger 154, shown for example in Fig. 6, arranged to engage a shoulder 156 on the extension 148 formed on the adjacent shell 138, the curved end faces 150 on the shells 138 riding up over the inclined surfaces 152 of the blocks 66 against the pressure of the 90 plungers 154 during the lowering of the spreaders out of the buttonholes.

The buttoning means comprise for each set means for taking the work from the receiving means and holding and positioning a button and entering and positioning a buttonhole together with buttonhole fly engaging means, and the buttoning operation is effected by relatively moving the said holding and positioning means and the 100 buttonhole fly engaging means. For taking the work from the receiving means and holding and positioning the buttons and positioning the buttonholes for the buttoning operations, each set has opposed relatively movable devices comprising a vertically disposed plunger, indicated generally by the numeral 158, (best shown in Fig. 21), and normally located above the corresponding fly holder, and an opposite coöperating 110 anvil 160 positioned below the corresponding button holder and having, in the form shown, a flat work engaging face. Each plunger 158 comprises a stem 162 (Fig. 21) having in its lower portion a slot 164 115 (Figs. 21 and 23) and extended therefrom to form a relatively thin blade 166. Each plunger 158 is adjustably supported in a sleeve 168 (Figs. 3, 5 and 21) by means of an adjusting nut 170 and a check nut 172 120 threaded on the upper portion of the plunger stem 162, the adjusting nut 170 resting upon the upper face of the adjacent plunger sleeve 168. By loosening the check nut 172 and turning the adjusting nut 170, 125 130

6
each plunger 158 can be adjusted up or down in its carrying sleeve 168 either to adjust the normal height of the plungers for button heads of different thicknesses or 5 for the purpose of raising the plungers to cause them to be entirely inclosed within their sleeves 168 if it is desired to use less than the entire number of plungers. A rather stiff coil spring 174 (Fig. 21) encircles each plunger stem 162, each spring 10 174 being seated upon a shoulder 176 formed between each plunger stem 162 and the slot 164 therein and bearing at its upper end against a shoulder 178 on the inside 15 face of each sleeve 168. Each slot 164 contains a block 180 pressed downwardly in the slot 164 by a coil spring 182 of sufficient strength to hold the said block normally at the lower end of the said slot and to 20 return it thereto after displacement in said slot. The upper end of each spring 182 bears against the upper end of the slot 164, each spring 182 being fastened at its lower end to a pin 184 on the adjacent block 180. 25 Secured at their upper ends by pins or screws to each block 180 and depending downwardly therefrom on opposite sides of each plunger blade 166 are two opposed springs 186, the lower ends of which, in 30 the normal positions of the parts, extend downwardly somewhat below the lower end of the plunger blade 166, as best shown in Fig. 21. These spring plungers 186 with the associated plunger blades 166 constitute 35 button head engaging devices, coöperating with the anvils 160 in positioning and holding the buttons for the buttoning operations. The spring plungers 186 are also designed to be caused to enter the buttoning 40 holes to position them for the buttoning operations. The inner faces of the spring plungers 186 of each pair near their lower ends are hollowed out at 188 (Fig. 22) to form between them a seat for the end portion 45 of each blade 166 and the recesses 188 terminate in inclined surfaces 190 (Figs. 21 and 22), so that, upon downward movement of the blades 166 relatively to the spring plungers 186, the blades 166 will 50 be forced to ride over the inclined faces 190 on the spring plungers 186, thus separating or spreading slightly the two spring plungers 186 of each set and holding them open, the adjacent blade 166 passing between 55 them. In order to prevent side play of the blade ends 166 of the plungers 158 in the sleeves 168, the plungers 158 have offset ribs 191 which give the plungers 158 a bearing at either side against adjacent walls of 60 the carrying sleeve 168. The ribs 191 also prevent side play of the spring plungers 186 with respect to the blades 166, the said spring plungers being received between the said ribs and being confined thereby against 65 sidewise movement (Figs. 21 and 23).

The plunger carrying sleeves 168 are supported in holders 192 (Fig. 5). In order that the sleeves 168 may be removably supported in the holders 192, the sleeves 168 near their upper ends are each provided with a groove adapted to receive the forked end of a member 194 which end embraces the grooved portion of the sleeve 168 below a shoulder formed on the said sleeve by the said groove, the forks 194 resting upon the upper faces of the holders 192 so that the sleeves 168 are prevented from being dislodged from the holders 192 by downward movement. The sleeves 168 are held against upward movement in the holders 192 by lateral projections 196, 197 (Fig. 21) on their front and rear faces respectively which projections engage shoulders 198, 199 (Fig. 1) formed by cutting away the front faces of the sleeve holders 192. 85 The sleeve holders 192 are mounted for movement with a head 200, provided at its ends with rearwardly directed extensions 202 (Figs. 3 and 5) adapted to slide up and down on correspondingly formed ways, indicated at 204, (Fig. 3) on the machine frame to permit the head 200 to be vertically reciprocated to lower and raise the plungers toward and from the work.

The head 200 is lowered and raised by 95 means of a bell crank lever indicated generally at 206 (Fig. 3) and fulcrumed on a shaft 208 extending transversely of the machine and supported at its ends in the machine frame. The bell crank lever 206 comprises two forwardly extending arms 210 carrying at their front ends rolls 212 mounted for sliding movement lengthwise of the machine in slots 214 in the extensions 202 of the head 200 and a single rearwardly extending arm 216 carrying a cam roll 218 arranged to travel in a cam path 219 on the outer face of the cam which has on its inner side the cam path 134.

The anvils 160 are carried on the front 110 ends of bars 220 and, in their operative position, are in vertical alinement with the plungers 158 and spring plungers 186. Each anvil bar 220 extends through and is carried in one of the guides 74. Each anvil bar 115 220 engages at its rear end a cross rod 222 (Figs. 1, 2 and 3) extending transversely of the machine and supported at its ends for turning movement in the frame 2. To permit the anvil bars 220 to be readily removed from the machine, and, at the same time, to provide for locking them in the machine when in use, the cross rod 222 has two opposite flattened sides (see for example Figs. 1 and 3), and each of the anvil bars 120 220 is split at its rear end and provided with a slot 224 adapted to receive the rod 222 in one position thereof and so shaped that, when thereafter the rod 222 is turned 125 in the slots 224 into the position shown, for 130

example, in Fig. 3, each anvil bar 220 is securely locked in engagement with the rod 222. To secure the rod 222 in locking engagement with the anvil bars 220, the said 5 rod extends at its ends outwardly beyond the outer faces of the side walls of the frame 2 and is provided at one end with a check nut 225 (Fig. 2), and at the other end with a cross pin 226 (Fig. 1), adapted to be 10 dropped into a recess in the outer face of the adjacent side wall of the frame 2, and a thumb head 227.

In order that the anvils 160 may be raised and lowered toward and from the 15 work, the anvil bars 220, intermediate between their ends, rest upon a cross bar 228 (Figs. 1, 2, 3 and 5), adjustably secured as by screws 229 to a bar 231 connecting two forwardly extending arms 230 of a bell 20 crank lever indicated generally at 232 and fulcrumed on a shaft 234 extending transversely of the machine and supported at its ends in the machine frame, the lever 232 having a single rearwardly extending arm 236 carrying a roll 238 (Fig. 3) which travels in a cam path 240 in the outer face of the cam 124 on the cam shaft 18. As 25 shown, the center anvil bar 220 is yieldingly held against the cross bar 228 by a spring 30 241.

To assist in supporting the button piece, indicated at B, when the buttons are placed in the button holders, each anvil bar 220 carries upstanding from its front end a 35 spring 242, the upper portions of the springs 242 being formed, as shown for example in Fig. 3, to extend just beneath the forks 68 in the normal position of the said forks and the free ends of the springs 242 projecting 40 slightly in front of the ends of the said forks so that, in introducing the buttons into the holders, the button piece B is passed under the forks 68 and over the springs 242 which serve as guides for the button 45 piece to facilitate the introduction of the buttons into their holders and also help to support and hold up the button piece, thus taking some of the weight from the button heads, the large quarter indicated at C falling 50 outside of the springs 242, as shown in Fig. 3. Preferably, to insure against catching in the work and particularly to prevent picking up the line of button fastening thread, the free ends of the springs 242 are 55 bent as shown, for example, at 243 in Fig. 6.

The construction of the above described parts is such and the operating mechanisms are so timed that, after the buttonholes have been alined with the plunger springs 186 through backward movement of the fly 60 holders (Fig. 8), the spreader blades 142 during this movement being opened to spread the buttonholes and hold them open to facilitate the passage of the spring plun- 65 gers 186 through the buttonholes (Fig. 9),

the plungers 158 are lowered by downward movement of the head 200 until the ends of the spring plungers 186 have entered and passed through the buttonholes (Figs. 10 and 11). Thereafter, the spreaders 142 are 70 swung downwardly out of the buttonholes and withdrawn to an inoperative position in the rear of the spring plungers 186 (Fig. 10) and the buttons are brought into alignment with the spring plungers 186 (Fig. 12) 75 through backward movement of the button holders. The buttonholes being thus positioned and held by the spring plungers 186 and the buttons being alined with the said 80 spring plungers and with the buttonholes held thereby, the plungers 158 are further lowered through continued downward movement of the head 200 to bring the spring plungers 186 into engagement with the 85 crowns of the button heads and, after the spring plungers 186 have engaged the heads of the buttons, the anvils 160 are moved upwardly through upward movement of lever 232 to support the buttons from below (Fig. 13). The buttons being thus held against 90 tipping movement in any direction, the button holders are thereafter withdrawn backwardly to an inoperative position (Fig. 15), leaving the buttons held between the spring 95 plungers 186 and anvils 160 in such a manner that the sides and bottom of each button head are left entirely free for the operation of the buttoning instrumentalities.

In order that the spring plungers 186 may hold the buttons as firmly as possible against 100 the anvils they are shaped to conform substantially to the transverse curvatures of the button heads by being curved somewhat at their lower ends, (as shown for example in Figs. 1 and 21), preferably in planes ex- 105 tending substantially at right angles to each other. Preferably, too, the blade ends 166 of the plungers 158 are similarly slightly curved (Figs. 21 and 23).

The buttonhole fly engaging means of 110 each set comprise a pair of buttoning fingers which, as shown, are integral with and form downwardly depending extensions of each sleeve 168 (Fig. 21), one at the front and the other at the back or rear of the said 115 sleeve, and two side tuckers 246 comprising springs adjustably connected at their upper ends to the corresponding projection 196 (Fig. 21) from the sleeve 168 by screws 248 received in slots 250 (Fig. 3) in the tuckers 120 246. The said buttonhole fly engaging means of each set, comprising two front and rear fingers 244 and two tuckers 246 may be termed a buttoner and will, for convenience, be frequently so referred to hereinafter. 125

The buttoners, being fixed with relation to the sleeves 168, are, of course, carried downwardly and upwardly with the said sleeves upon movement of the head 200. In the 130 operation of the machine, after the spring

plungers 186 and anvils 160 have been oppositely moved to clamp the buttons and the button holders have been withdrawn to an inoperative position, the buttonhole fly engaging instrumentalities being alined thereby with the button heads and the buttonholes being held directly above the heads of the buttons, a further downward movement of the head 200 is effected through its operating lever 206. During this downward movement of the head 200, the buttoners are brought substantially simultaneously down upon the buttonhole fly and then forced still farther downwardly to crowd the edges of the buttonholes down over the upstanding button heads, the buttoners acting at substantially the same time upon the fly near each buttonhole upon the sides and at the front and rear thereof.

The buttoning fingers 244, as shown, project downwardly slightly below the lower ends of the tuckers 246 so that the fingers 244 engage the buttonhole fly slightly in advance of the engagement of the tuckers therewith and push the stock adjacent to each buttonhole downwardly from the position shown in Fig. 13 into engagement with the button heads, as illustrated in Fig. 15. In order that this pushing action of the said fingers 244 may be effectively accomplished and the said stock properly positioned and conditioned for the action of the tuckers, the said fingers are, as shown, especially shaped and arranged to carry the stock into engagement with and around it over the heads of the buttons smoothly and without wrinkling or puckering. With this in view, the fingers 244 are formed with outturned ends arranged to engage the stock near each buttonhole at the front and rear of the buttonhole and positioned and shaped to slightly more than straddle the adjacent button head so as to push the stock against the button head without pinching the stock. As the buttoning fingers 244 bring the stock against the button heads (Fig. 15), the tuckers 246 are brought into engagement with the buttonhole fly directly above the head of each button at opposite sides and at the edges of each buttonhole (Figs. 15 and 16), the tuckers engaging the edge binding stitches of the buttonholes (Fig. 16).

It will be understood that, during the said downward movement of the head 200, the spring plungers 186 are prevented from partaking thereof by their engagement with the heads of the buttons, the eyes of which are rigidly upheld by the anvils 160. During this movement of the head 200, the blade ends 166 of the plungers 158 are forced over the inclined surfaces 190 on the inside faces of the spring plungers 186, the blade ends 166 wedging the two spring plungers 186 of each set apart and passing downwardly between the said spring plungers into en-

gagement with the crowns of the button heads. This relative movement of the blades 166 and spring plungers 186 is permitted by the springs 182, the blocks 180 traveling in the slots 164 in the plungers 158 upon downward movement of the head 200 after the spring plungers 186 have engaged the heads of the buttons. The springs 182 and 174 are so proportioned as to relative strength that the springs 182 are compressed enough more rapidly than the springs 174 to cause the spring plungers 186 to be separated and the blade ends 166 to engage the crowns of the button heads before the tuckers 246 engage the edge binding stitches of the buttonholes. In consequence, the heads of the buttons are each engaged shortly before the buttoning action of the tuckers by the three point contact made by the separator end 166 of the plunger 158 and the ends of the associated spring plungers 186 (Fig. 18) and are solidly clamped between these instrumentalities and the anvils 160. Furthermore, this construction is such that not only is the entire downward movement of the head 200, after the spring plungers 186 engage the heads of the buttons, yieldingly effected but the springs 182 of each set yield under pressure of the work and provide for positioning the button head engaging instrumentalities according to differences in contour and thickness of the button heads while the springs 174 subsequently increase the pressure of the button head engaging instrumentalities.

The separation of the spring plungers 186 carries the two springs of each pair outwardly toward and near the edge of the button head, as best shown in Fig. 18, the button head being nearly covered thereby to prevent the tuckers 246 striking and nicking or marring the button head as they are brought into engagement with the fly at the edges of the buttonhole. Moreover, the tuckers 246, which yieldingly overlap the spring plungers 186 upon the outer sides of the said springs, are, of course, spread apart by the spreading action of these springs so that the tuckers are positioned to insure that they will engage the buttonhole upon the opposite sides thereof exactly at the edge. At the same time, the spreading of the spring plungers and tuckers operates to spread the buttonholes substantially, thus facilitating the buttoning operation of the tuckers by carrying the sides of the buttonhole out toward the edge of the button head on opposite sides thereof. As a result, upon continued downward movement of the head 200 while the stock is held smoothly against the button head by the pushing action of the fingers 244, in order to effect the buttoning operations, the tuckers, operating in engagement with the edges of the buttonholes, merely have to strip the stock on opposite

sides of each buttonhole off the spring plungers and carry it over the edge of the adjacent button head. To further facilitate the buttoning action of the tuckers and to insure that the buttoning operations may be satisfactorily completed, the tuckers are shaped (as best shown in Fig. 24) to conform substantially to the contour of the button heads and to tuck the stock at the edge of each buttonhole on opposite sides thereof under the head of the adjacent button and then to crowd the stock snugly against the eye of the button after the tuckers have carried the said stock under the button head. With this in view, each of the tuckers is provided with an inturned end or lip (Fig. 24) and this end and the portion of the tucker adjacent thereto are curved to conform substantially to the curvature of the edge circumference of the button head, as clearly shown in Fig. 24. After the completion of the buttoning operations, the head 200 is again raised and the anvils 160 are swung downwardly sufficiently to release the work from the plungers, buttoners and anvils.

For automatically discharging the buttoned upper from the machine after it has been thus released, the machine, as shown, is provided with an ejector comprising a horizontal bar 252 extending transversely of the machine and arranged for sliding movement in a groove 254 (Fig. 3) in the upper face of the center anvil bar 220. The ejector bar 252 is operated by means of a pair of levers indicated generally at 256, (Figs. 1 and 3) each comprising two pivotally connected arms of which one arm 258 is pivoted at its free end to the ejector bar 252 and the other arm 260 is bent, as shown for example in Fig. 3, and is provided with a slot 262 extending around the bend in said arm. In each of the slots 262 travels a roll 264 projecting from the anvil lever 232. When the anvil lever 232 is operated by its cam to raise the anvils 160 into position to support the button eyes and then to lower the said anvils into their normal inoperative position (shown for example in Figs. 2, 3 and 4), the rolls 264 travel up and down in the short portions of the slots 262 and no movement is imparted to the ejector bar 252. After the release of the work at the conclusion of the buttoning operations however, the anvil lever 232 is caused to have a further downward movement from the position shown in Figs. 2, 3 and 4 into the position indicated in Fig. 19 with the result that the rolls 264 are caused to travel backwardly in the long portions of the slots 262 and the levers 256 are thereby operated to move the ejector bar 252 forwardly to discharge the buttoned upper from the machine (Fig. 19).

In order to adapt the machine for operating upon uppers of different lengths, widths

and patterns, the machine has provision for making various adjustments of the operating instrumentalities. In order to adjust the operating instrumentalities of the machine for operating upon uppers of different lengths or having differently spaced buttons and buttonholes, the machine, as shown, is constructed and arranged so that the different sets may be simultaneously moved toward or from each other upon movement of an adjusting treadle which operates to move at the same time the sleeve holders 192 and the guides 74 so that, upon movement of the said treadle, the plungers, buttoners, button and fly holders and the anvils are simultaneously adjusted toward or from each other. Preferably, and as shown, the center set is fixed against movement transversely of the machine and the other sets are movable toward and from the center set. In order to provide for movement transversely of the machine of each of the sleeve holders 192 except the center holder, the said sleeve holders have pivotal connections at 266 (Fig. 5) with blocks 268 having rearward extensions 270 arranged to slide transversely of the machine in a cross slot 272 in the head 200. Cap plates 274 pinned to the extensions 270 of the blocks 268 slide in recessed ways 276 in the head 200 so that the sleeve holders 192 are secured to the head 200 for up and down movement therewith and, at the same time, may slide in the head 200 transversely of the machine. For operating the blocks 268 to move the holders 192 and, consequently, the plungers and buttoners carried thereby toward or from each other, each of the cap plates 274 has pivoted to it, as by a set screw 277, one end of a toggle link 278, the links 278 on opposite sides of the center set extending in opposite directions. At their other ends, the toggle links 278 are pivoted to a lever 280 constituting a common toggle link and fulcrumed on the head 200, as by a screw 282. The construction is such that there are in effect two sets of toggles of each of which toggles the center link 280 forms one arm. At its upper end, the center link 280 carries a roll 283 (Fig. 3) traveling in a vertical slot 284 (Fig. 5) in an extension 286 of a controller 288 mounted to be shiftable transversely of the machine along parallel rods 290 supported at their ends in the machine frame. The controller 288 is operated by means of a bell crank indicated generally at 292 and fulcrumed at 294 to the top of the machine frame 2 (Figs. 3 and 5), one arm 296 of the bell crank 292 having a pin and slot connection with the controller 288, which connection comprises a pin 298 (Figs. 3 and 5) on the said controller received in a slot 300 in the arm 296 of the bell crank 292. The other arm 302 (Fig. 5) of the bell crank 292 has a universal joint connection with a rock shaft 304 supported 130

in a lug 306 on the machine frame and extending through a bearing in the adjacent side wall of the said frame. The rock shaft 304 at its outer end is adjustably secured as 5 by a set screw 308 to an arm 310 which, in turn, is linked to a foot treadle (not shown) by a rod 312 (Figs. 2 and 5), the said foot treadle constituting the adjusting treadle before referred to. The illustrated universal 10 joint connection between the arm 302 of the bell crank 292 and the rock shaft 304 comprises a box 314 (Fig. 5) pivoted to a reduced end 316 of the lever arm 302 and formed to receive a ball 318 on an arm 320 15 on the rock shaft 304, the ball 318 having oscillating movements in two directions in the box 314. For regulating the amount of pressure on the adjusting treadle required to move the controller 288, there is provided 20 a friction brake comprising a band 322 encircling the rock shaft 304. One end of the band 322 is secured by a pin 324 to a block 326 formed on the lug 306 and the other end of the band 322 carries a screw threaded ex- 25 tension supported in a strap 328 secured to the block 326 as by screws 330 and provided with an adjusting nut 332 by means of which the friction of the brake band 322 on the rock shaft 304 may be regulated. The pin 324 at its outer end is received in a curved slot 334 in the inner end of the arm 310 and constitutes a stop to limit adjustably the 30 amount of depression of the treadle, adjustment of the position of the arm 310 on the rock shaft 304 by means of the set screw 308 regulating the amount of travel of the arm 310 and consequently of the adjusting treadle.

For moving the guides 74 to adjust the fly 40 holders and anvils simultaneously with the adjustment of the buttoners and plungers and correspondingly, each of the guides 74, except the center guide, which, as above stated, is stationary, is provided with a cap plate 336 (Fig. 5) connecting the upstanding projections 76 on the guides 74 and the cap plates 336 are connected with a downwardly extending arm 338 of the controller 288 by a toggle arrangement similar to the 45 above described arrangement for operating the sleeve holders 192, the toggle arrangement for operating the guides 74 transversely of the machine upon movement of the controller 288 comprising a series of links 340 pivoted at their outer ends to the several cap plates 336 and pivoted at their inner ends to a lever 342 constituting a common central toggle link and fulcrumed as by a set screw 344 to a cross piece 346 of the tie plate 82. 50 The common center link 342 at its forward end is connected to the arm 338 of the controller 288 by a pin and slot connection comprising a roll 348 on the said link 342 received in a slot 350 in the lower end of the 55 arm 338 of the controller 288. The two sets 60

of short toggle links 340 on opposite sides of the center link 342 extend in reverse directions, the arrangement in this respect being similar to the above described arrangement of toggle links for operating the sleeve 70 holders 192. Upon movement of the adjusting treadle, the controller 288 is operated through the above described connections to move at the same time and correspondingly the movable sleeve holders 192 through the 75 toggles 278, 280 toward or from the fixed center sleeve holder 192 and to move the movable guides 74 through the toggles 340, 342 toward or from the fixed center guide 74, with the result that, as above suggested, 80 upon movement of the said adjusting treadle, at the same time and correspondingly the plungers, buttoners, button and fly holders and anvils are adjusted toward or from the fixed center set. To secure the central set 85 against adjusting movement transversely of the machine, the central sleeve holder 192 is fixed, as by set screws 352 (Fig. 3), to the head 200 and the central guide 74 is secured to the tie plate 82. Plates 351 (Fig. 2) limit 90 the amount of adjusting movement of the holders 192 in the head 200.

To provide for suitable adjustments of the plungers and buttoners for operating upon uppers cut upon patterns differing in the curve or sweep of the outer edge of the buttonhole fly and consequently in the line or curve upon which the buttons and buttonholes are set, in the illustrated construction each of the holders 192 except the center 100 holder is, as above stated, pivoted at 266 to the head 200 and there are provided for each of said holders adjusting screws 353 and 354 (Fig. 5), the screws 353 being threaded through the holders and bearing 105 against the outer faces of the blocks 268 and the screws 354 passing loosely through slots 359 in the holders 192 and being threaded into the blocks 268 so that upon loosening the screws 354 and turning up the screws 353 110 the sleeve holders 192 will be swung outwardly about their pivots 266. It will also be understood that a corresponding adjustment of the button and fly holders may be effected by moving the slide bars 72 and 90 115 lengthwise of the machine, such movement of the bars 72 and 90 being permitted by the manner in which they are, as above stated, adjustably secured at their rear ends in the shells 98 and 96 by the screws 94 and 92. 120 Preferably, too, the anvils 160 are made adjustable lengthwise of the anvil bars 220 by having their stems adjustably secured in slots 355 in the anvil bars 220, as by nuts 357 threaded on the said stems (Fig. 3).

The illustrated machine also has provision for adjusting the buttoners and plungers to adapt them for operating upon uppers having buttonholes set in different angular positions. To this end, the sleeves 168 which 125

- carry the plungers and buttoners may be turned within their holders 192 by means of the forks 194 which engage flattened faces on the upper portions of the sleeves 168.
- 5 Each of the forks 194 carries a spring pressed plunger 356, the plungers 356 extending through the forks 194 and being adapted to engage one or another of a series of holes in the upper faces of each of the
- 10 holders 192 and constituting means for permitting the sleeves 168 to be turned within their holders 192 and then locked in adjusted position. For limiting the extent of turning movement of the sleeves 168 in either direction, each sleeve 168 is provided with a pin 358 (Figs. 3 and 21) traveling in a groove in the inside rear face of the adjacent holder 192, opposed shoulders formed at either end of each of said grooves determining the extent of movement of each pin 358 either way and consequently limiting the extent of turning movement of each sleeve 168 within its holder 192.
- The operation of the machine may be summarized as follows: Before introducing the work into the machine, the various sets of operating instrumentalities may be adjusted according to the length of upper to be operated upon and according to the spacing of the buttonholes and buttons thereon by movement of the positioning treadle one way or the other. The plungers 158 and buttoners 244, 246 may be turned by movement of their carrying sleeves 168 within the sleeve holders 192 to adjust the angular positions of the said plungers and buttoners according to the angular positions of the buttonholes. The holders 192 may be adjusted by means of the adjusting screws 353 and 354 to cause the line of curvature of the plungers and buttoners to correspond to the curve upon which the buttons and buttonholes are set and the button and fly holders and the anvils may be adjusted similarly by moving the slide bars 72 and 90 lengthwise of the machine and the anvils 160 lengthwise of the anvil bars 220. After these preliminary adjustments, the work, in which previously the desired number of buttonholes have been made and to which a corresponding number of buttons have already been attached, is introduced into the machine, as shown in Figs. 3, 4, 6 and 7, by placing the button eyes between the spring fingers 70 of the holders, the button piece B being thrust between the button guides 68 and the supporting springs 242. The buttonhole fly A is then carried over and rested upon the fly holder forks 88, the buttonhole spreader blades 142 projecting upwardly through the buttonholes, the large quarter C falling outside of the springs 242. After the work has been thus placed in the work receiving means, the positioning treadle may be moved still farther, if necessary, to adjust the various sets of instrumentalities more exactly. The starting treadle is then depressed to throw in the clutch and start the machine whereupon the fly holders are moved backwardly 70 toward the machine to bring the buttonholes into alignment with the spring plungers 186 (Fig. 8). During this movement of the fly holders, the spreader arms 136 are forced apart to cause the blades 142 to open the buttonholes and hold them open for the passage therethrough of the spring plungers 186 (Figs. 8 and 9). After the buttonholes have been thus aligned with the spring plungers 186 and while they are held open by the spreaders, the plungers 158 are lowered by downward movement of the head 200 to cause the spring plungers 186 to enter and pass downwardly through the buttonholes (Figs. 10 and 11). After the 85 spring plungers 186 have passed through the buttonholes, continued backward movement of the fly holders while the buttonholders are held stationary causes the buttonhole spreaders to be swung downwardly 90 and then moved backwardly to withdraw the spreader blades 142 from the buttonholes and move them into an inoperative position (Fig. 10). Thereupon, the buttonholders are moved backwardly toward the 95 machine to bring the buttons beneath and in alignment with the spring plungers 186 and with the buttonholes held thereby (Fig. 12). Thereafter, further downward movement of the head 200 causes the spring plungers 186 to be lowered into engagement with the crowns of the button heads (Figs. 13 and 14). After the lower ends of the spring plungers 186 have engaged the heads of the buttons, the anvils 160 are moved upwardly 105 to support the eyes of the buttons from below (Fig. 13). The buttons being thus held against tipping movement in any direction by the spring plungers 186 and the anvils 160 (Fig. 13), the button holders are withdrawn to an inoperative position (Fig. 15) and, thereafter, during continued downward movement of the head 200, the buttoners 244, 246 are carried simultaneously 110 (Figs. 15 and 16) down upon the buttonhole fly and then caused to carry the edges of the buttonholes downwardly over the heads of the buttons (Figs. 17 and 18). During this downward movement of the head 200, the separator ends 166 of the plungers 158 operate to spread the spring plungers 186 and tuckers 246 so that, shortly before the buttoning action of the tuckers, each button head is engaged centrally by the separator end 166 of a plunger 158 and 115 oppositely near its edge by two spring plungers 186 which protect the edge of the button head against injury from the tuckers and at the same time slightly open the adjacent buttonhole thereby carrying the edges 120 125 130

of the buttonhole out nearly to the edge of the button head. The tuckers then strip the stock at the edges of the buttonholes off the spring plungers, carry it under the heads of the buttons and tuck it snugly against the eyes of the buttons.

After the completion of the buttoning operations, the head 200 is raised and the anvils 160 are swung downwardly to cause the plunger blades 166, spring plungers 186, buttoners 244, 246 and anvils 160 to release the work whereupon continued downward movement of the anvil lever 232 causes the ejector bar 252 to be operated, as illustrated in Fig. 19, to discharge the work from the machine. Thereafter, the parts are restored to their initial positions.

Having fully explained my invention and described in what manner the same may conveniently be embodied, what I claim as new and desire to secure by Letters Patent of the United States is:

1. In a machine of the class described, means for positioning a button constructed and arranged to position a buttonhole also, buttonhole fly engaging means, and mechanism for relatively moving said means to effect a buttoning operation.

2. In a machine of the class described, means for positioning a button constructed and arranged to enter and position a buttonhole also, buttonhole fly engaging means, and operating mechanism for relatively moving said means to effect a buttoning operation.

3. In a machine of the class described, means for positioning a button constructed and arranged to enter and position a buttonhole also, buttonhole fly engaging means, and mechanism for operating said fly engaging means to effect a buttoning operation.

4. In a machine of the class described, buttonhole fly engaging means, means for positioning a button, said button positioning means being constructed and arranged to position a buttonhole over the head of the button, and operating mechanism for relatively moving said means to effect a buttoning operation.

5. In a buttoning machine, means for engaging a buttonhole fly adjacent to a buttonhole, button holding means constructed to support a button and to enter a buttonhole to position the buttonhole fly between the button and said fly engaging means, and mechanism for relatively moving said means to effect a buttoning operation.

6. In a buttoning machine, means for engaging a buttonhole fly, work holding means including means movable through a buttonhole into engagement with a button, and mechanism for relatively moving said means to effect a buttoning operation.

7. In a buttoning machine, means for engaging a buttonhole fly, means for position-

ing a button constructed and arranged to spread a buttonhole, and mechanism for relatively moving said means to effect a buttoning operation.

8. In a buttoning machine, work holding means comprising a device constructed to enter a buttonhole and to engage a button and means coöperating with said device to sustain the button, means to engage a buttonhole fly adjacent to the buttonhole, and mechanism for relatively moving said work holding and fly engaging means to effect a buttoning operation.

9. In a machine of the class described, means for relatively moving a button and buttonhole in such a manner as to effect a buttoning operation with respect to said button and buttonhole, and means operating to discharge the work from the machine at the conclusion of the buttoning operation.

10. In a machine of the class described, means for positioning a button, buttonhole fly engaging means, mechanism for relatively moving said means to effect a buttoning operation, and means for discharging the buttoned work from the machine.

11. In a machine of the class described, means for positioning a button and buttonhole, buttonhole fly engaging means, mechanism for operating said means to effect a buttoning operation, and means for discharging the work from the machine at the conclusion of the buttoning operation.

12. In a machine of the class described, means for positioning a button, buttonhole fly engaging means, mechanism for operating said means in such a manner as to effect a buttoning operation, and means operating automatically to discharge the work from the machine at the conclusion of a buttoning operation.

13. In a machine of the class described, buttonhole fly engaging means, means for holding against tipping movement in any direction a button attached to a button piece, and operating mechanism for relatively moving said means to effect a buttoning operation.

14. In a machine of the class described, buttonhole fly engaging means, means for yieldingly holding against tipping movement a button attached to a button piece, and operating mechanism for relatively moving said means to effect a buttoning operation.

15. In a machine of the class described, means for clamping against tipping movement a button attached to a button piece, buttonhole fly engaging means, and operating mechanism for relatively moving said means to effect a buttoning operation.

16. In a machine of the class described, opposed relatively movable devices constructed and arranged to hold between them a button attached to a button piece, button-

- hole fly engaging means, and operating mechanism for relatively moving said devices and means to effect a buttoning operation.
- 5 17. In a buttoning machine, buttonhole fly engaging means, button holding means comprising a plurality of devices relatively movable to exert pressure on a button attached to a button piece, and mechanism for 70 relatively moving said fly engaging and button holding means to effect a buttoning operation.
- 10 18. In a buttoning machine, buttonhole fly engaging means, a plurality of movable devices constructed to sustain between them for a buttoning operation a button attached to a button piece, and mechanism for 75 relatively moving said means and devices to effect a buttoning operation.
- 15 19. In a buttoning machine, buttonhole fly engaging means, means for holding for a buttoning operation a button attached to a button piece, and mechanism for relatively moving said button holding and fly engaging means to effect a buttoning operation, said button holding means being movable into and out of position to support a button for the coöperative action of said fly engaging means.
- 20 20. In a buttoning machine, buttonhole fly engaging means, means for clamping a button attached to a button piece to hold the button from movement in a direction transverse to the plane of the button piece and mechanism for relatively moving said button holding and fly engaging means to effect a buttoning operation through co-operative action of said means, said button holding and fly engaging means being relatively movable into and out of position for their said coöperative action.
- 25 21. In a buttoning machine, button holding means comprising button sustaining devices movable relatively to each other into and out of position to sustain for a buttoning operation a button attached to a button piece, buttonhole fly engaging means, and mechanism for relatively moving said button holding and fly engaging means to effect a buttoning operation.
- 30 22. In a buttoning machine, means for holding a button in such a manner as to leave free the bottom of the button head, means for engaging a buttonhole fly adjacent to a buttonhole, and mechanism for relatively moving said means to effect a buttoning operation.
- 35 23. In a buttoning machine, fly engaging means, means for supporting a button with the sides and bottom of its head entirely free for a buttoning operation, and mechanism for relatively moving said means to effect a buttoning operation.
- 40 24. In a machine of the class described, button holding means comprising means for 80 engaging the head of a button and means for supporting the eye of the button, buttonhole fly engaging means, and operating mechanism for relatively moving said means to effect a buttoning operation.
- 45 25. In a buttoning machine, button holding means comprising a plunger to engage the crown of a button head and an anvil to support the eye of the button, buttonhole fly engaging means, and mechanism for 85 relatively moving said means to effect a buttoning operation.
- 50 26. In a machine of the class described, button holding means comprising means for engaging the head of a button and means for supporting the eye of the button, buttonhole fly engaging means, and mechanism for 90 moving said fly engaging means to cause interengagement between the button and a corresponding buttonhole.
- 55 27. In a machine of the class described, buttonhole fly engaging means, means for holding a button attached to a button piece to prevent the button from moving relatively to the holding means in a direction 95 transverse to the plane of the button piece, and operating mechanism constructed and arranged to move said button holding means into position to hold the button and thereafter to effect a relative movement of said button holding and fly engaging means in such a manner as to effect a buttoning operation.
- 60 28. In a machine of the class described, button holding means comprising means for engaging the head of a button and supporting the eye of the button, buttonhole fly engaging means, and operating mechanism for causing holding engagement of said first named means with the button and for thereafter relatively moving said button 100 holding and fly engaging means to effect a buttoning operation.
- 65 29. In a machine of the class described, button holding means comprising means movable into engagement with the head of 110 a button and means oppositely movable into position to support the eye of the button, buttonhole fly engaging means, and mechanism for moving both said button holding means into holding relation to the button 115 and for thereafter relatively moving said button holding and fly engaging means to effect a buttoning operation.
- 70 30. In a buttoning machine, work holding means comprising a plurality of opposed 120 relatively movable devices constructed to hold between them for a buttoning operation a button attached to a button piece, buttonhole fly engaging means, and mechanism for relatively moving said work holding means and said buttonhole fly engaging means in a direction substantially parallel to the line of support of the button to effect the buttoning operation.
- 75 31. In a machine of the class described, 125

- buttonhole fly engaging means, means for holding a button and positioning a buttonhole, and operating mechanism for relatively moving said means to cause said holding and positioning means to enter a buttonhole and engage a button and for thereafter relatively moving said means to effect a buttoning operation.
32. In a buttoning machine, means for engaging a buttonhole fly adjacent to a buttonhole, button holding means having parts constructed to enter a buttonhole and to spread the buttonhole, and mechanism for relatively moving said means to effect a buttoning operation.
33. In a buttoning machine, means for holding a button and spreading a buttonhole, means for engaging the buttonhole fly at the opposite edges of the buttonhole, and mechanism for relatively moving said means to effect a buttoning operation.
34. In a buttoning machine, buttoning means arranged to engage the edges of a buttonhole, and mechanism for operating said means to effect a buttoning operation.
35. In a machine of the class described, buttoning means arranged to engage a buttonhole fly upon opposite sides of a buttonhole and at the edges of the buttonhole, and mechanism for operating said means to effect a buttoning operation.
36. In a buttoning machine, means for engaging a button, buttonhole fly engaging means constructed to tuck opposite edges of a buttonhole under the head of the button, and mechanism for relatively moving said means to effect a buttoning operation.
37. In a buttoning machine, means constructed and arranged to force the edges of a buttonhole over the head of a button and to tuck said edges of the buttonhole under the head of the button, and mechanism for operating said means.
38. In a buttoning machine, means to position a button and buttonhole for a buttoning operation, buttonhole fly engaging means operating to tuck opposite edges of a buttonhole under the head of the button, and mechanism for moving said fly engaging means to effect a buttoning operation.
39. In a machine of the class described, means for holding a button attached to a button piece, buttonhole fly engaging means acting upon opposite edges of a buttonhole, and operating mechanism for relatively moving said means to effect a buttoning operation.
40. In a buttoning machine, means to position a button constructed and arranged to position a buttonhole also, fly engaging means constructed to bear on a buttonhole fly upon opposite sides of the buttonhole, and mechanism for relatively moving said means to effect a buttoning operation.
41. In a machine of the class described, means for engaging a button, means for engaging a buttonhole fly adjacent to a buttonhole upon the sides and at the front and rear of the buttonhole, and mechanism for relatively moving said means to effect a buttoning operation.
42. In a machine of the class described, means for holding a button, means for engaging a buttonhole fly upon the sides and at the front and rear of a buttonhole, and mechanism for moving said fly engaging means to effect a buttoning operation.
43. In a buttoning machine, means for holding a button, buttoning instrumentalities comprising a pair of tuckers arranged to engage a buttonhole fly at the edges of a buttonhole and each having its work engaging face shaped to conform substantially to the contour of the button head, and mechanism for relatively moving said means and said tuckers to effect a buttoning operation.
44. In a buttoning machine, means for engaging a buttonhole fly, and mechanism for operating said fly engaging means to cause said means to tuck the stock at the side of and adjacent to a buttonhole under the head of a button and crowd it snugly against the eye of the button.
45. In a buttoning machine, means for holding a button for a buttoning operation, and tuckers arranged to carry the stock adjacent to a buttonhole over the edge of the button head and provided with inturned lips adapted to crowd the said stock snugly against the eye of the button.
46. In a buttoning machine, opposed tuckers shaped to conform substantially to the contour of a button head.
47. In a buttoning machine, means constructed and arranged to engage a buttonhole fly adjacent to a buttonhole, said means being shaped to conform substantially to the contour of the button head, and mechanism for operating said fly engaging means to cause said means to carry the material of the buttonhole fly over the edge of a button head.
48. A tucker having an inturned end, said end and the portion of the tucker adjacent thereto being curved to conform to the curvature of the edge circumference of a button head.
49. In a buttoning machine, means for holding a button for a buttoning operation, relatively movable devices for engaging a buttonhole fly upon opposite sides of a buttonhole, and at the edges of the buttonhole, and mechanism for relatively moving said means and said devices to effect a buttoning operation.
50. In a buttoning machine, means for holding a button for a buttoning operation, opposed devices movable to engage a buttonhole fly at opposite edges of a buttonhole, said devices having portions spaced

- apart for engagement with the edges of the buttonhole, and mechanism for relatively moving said means and said devices to effect a buttoning operation.
- 5 51. In a buttoning machine, means for holding a button for a buttoning operation, devices yieldingly movable toward and from each other for engaging a buttonhole fly adjacent to a buttonhole, and mechanism for relatively moving said means and said devices to effect a buttoning operation. 70
- 10 52. In a buttoning machine, means to engage the crown of a button head, an anvil to support the button eye and coöperating with said means to hold the button, said means being constructed and shaped to enter a buttonhole, buttonhole fly engaging means, and operating mechanism for said means. 75
- 15 53. In a buttoning machine, button holding means comprising means for engaging the crown of a button head and means for supporting the eye of the button coöperating with said first named means to hold the button in an upright position, buttonhole fly engaging means, and mechanism for relatively moving said button holding and fly engaging means to effect a buttoning operation. 80
- 20 54. In a buttoning machine, an anvil for supporting the eye of a button, means to engage the crown of the head of the button supported by said anvil, a pair of tuckers for engaging a buttonhole fly, and supporting means for said tuckers and said engaging means enabling them to have a relative yielding movement toward and from said anvil. 85
- 25 55. In a buttoning machine, button holding means having a device arranged to engage the crown of a button head, a pair of tuckers arranged to engage a buttonhole fly, and supporting mechanism enabling said device and said tuckers to have a relative movement toward and from the button. 90
- 30 56. In a buttoning machine, button supporting means comprising a pair of members arranged to engage the head of a button and to enter a buttonhole, means for spreading said members apart while they are positioned in the buttonhole, and means for engaging the buttonhole fly to cause the passage of the button through the buttonhole. 95
- 35 57. In a buttoning machine, means for supporting a button for a buttoning operation including a part arranged to enter and position a buttonhole, a pair of tuckers shaped and positioned to engage the buttonhole fly at the sides of the buttonhole, means for spreading said tuckers apart to facilitate the entrance of the button head in the buttonhole, and operating mechanism for relatively moving said tuckers and supporting means to effect a buttoning operation. 100
- 40 58. In a buttoning machine, an anvil to support the eye of a button, a pair of plungers arranged to engage the head of the button supported by said anvil, a pair of tuckers positioned on opposite sides of said plungers, and means operating through said plungers to spread said tuckers. 105
- 45 59. In a buttoning machine, work receiving means and buttoning means, the work receiving means being constructed and arranged to position a button attached to a button piece upon the initial presentation of the work to the machine, said receiving means and buttoning means being mounted for relative movement to effect a presentation of the work to the buttoning means. 110
- 50 60. In a buttoning machine, buttoning means, and work receiving means arranged to position the work in its initial presentation to the machine, said work receiving means being constructed and arranged for movement to present the work to said buttoning means. 115
- 55 61. In a buttoning machine, buttoning means, and work receiving means mounted for movement from work receiving position into work presenting relationship to said buttoning means and into an additional position inoperative with relation to said buttoning means. 120
- 60 62. In a buttoning machine, buttoning means, work receiving means, and mechanism for moving said receiving means to present the work to the buttoning means and for thereafter moving said receiving means into inoperative position with relation to the buttoning means. 125
- 65 63. In a machine of the class described, work receiving means constructed and arranged to receive a button attached to a button piece upon the initial presentation of the work to the machine, buttoning means, and mechanism for relatively moving said means to present the work to the buttoning means. 130
- 70 64. In a machine of the class described, work receiving means constructed and arranged to receive a button attached to a button piece upon the initial presentation of the work to the machine, buttoning means, and mechanism for relatively moving said means in such a manner as to cause the work to be presented to the buttoning means and a buttoning operation to be effected with respect to said work. 135
- 75 65. In a machine of the class described, button receiving means constructed and arranged to position a button upon the initial presentation of the work to the machine, buttoning means, and mechanism for relatively moving said means to present the button to the buttoning means. 140
- 80 66. In a machine of the class described, buttoning means, work receiving means constructed and arranged to position the work in its initial presentation to the machine, 145

and mechanism for moving said receiving means from work receiving position to a position to present the work to the buttoning means.

5 67. In a machine of the class described, buttoning means, work receiving means constructed and arranged to position the work in its initial presentation to the machine, and mechanism for moving said receiving means from work receiving position to a position to present the work to the buttoning means and for thereafter causing a buttoning operation to be effected.

15 68. In a machine of the class described, buttoning means, button receiving means constructed and arranged to position a button in the initial presentation of the work to the machine, and mechanism for moving said receiving means to present a button to the buttoning means.

20 69. In a machine of the class described, buttoning means, work receiving means normally in an inoperative position with respect to the buttoning means, and mechanism for relatively moving said means into operative relation to each other.

25 70. In a machine of the class described, buttoning means, work receiving means normally out of alinement with the buttoning means to facilitate introducing the work into the receiving means, said receiving means being constructed and arranged to position the work in its initial presentation to the machine, and operating mechanism for relatively moving said means to present the work to the buttoning means.

30 71. In a machine of the class described, buttoning means, button receiving means normally out of alinement with the buttoning means, said receiving means being constructed and arranged to position the work in its initial presentation to the machine, and mechanism for moving said receiving means to carry a button into alinement with the buttoning means.

35 72. In a buttoning machine, means for performing a buttoning operation, means for moving a button into operative relationship to said means, buttonhole fly receiving means, and means for moving said receiving means to present the fly to the first named means.

40 73. In a buttoning machine, work positioning means, work receiving means mounted for movement into an operative position in alinement with said positioning means and into a work receiving position in advance of said operative position, and mechanism coöperating with said positioning means to effect a buttoning operation.

45 74. In a buttoning machine, button receiving means, mechanism for moving said means into and out of receiving position, devices movable transversely of the path of movement of said means to engage and posi-

tion for a buttoning operation a button carried by said means, and means coöperating with said devices to effect a buttoning operation.

50 75. In a buttoning machine, button holding means, buttonhole fly receiving means arranged to effect an initial positioning of a buttonhole, and means coöperating with said holding and receiving means to effect a buttoning operation. 75

76. In a machine of the class described, button receiving means constructed and arranged to receive a button attached to a button piece, buttonhole fly receiving means, buttoning means, and mechanism for relatively moving said means to present a button and buttonhole to the buttoning means. 80

77. In a machine of the class described, buttonhole fly receiving means, buttoning means, and mechanism for effecting a relative movement of said means to present the work to the buttoning means, said receiving means having provision for preventing accidental disengagement of the fly from the receiving means during said relative 90 movement.

78. In a machine of the class described, work receiving means arranged to position a buttonhole in the initial presentation of the work to the machine, buttoning means, and mechanism for relatively moving said receiving means and said buttoning means to present the work to the buttoning means. 95

79. In a machine of the class described, work receiving means including means for supporting a buttonhole fly adjacent to a buttonhole and means for entering the buttonhole, buttoning means, and mechanism for relatively moving said receiving and buttoning means to present the work to the buttoning means. 100

80. In a machine of the class described, button receiving means constructed and arranged to receive a button attached to a button piece, buttonhole fly receiving means including means for entering a buttonhole, buttoning means, and mechanism for effecting relative movement of said buttoning means and said receiving means to present a button and buttonhole to the buttoning means. 110 115

81. In a buttoning machine, work receiving means, means for performing a buttoning operation, said means being mounted for relative movement into position to present the work for a buttoning operation, and means for discharging the work from the machine after the completion of the buttoning operation. 120

82. In a buttoning machine, means for performing a buttoning operation, work receiving means mounted for movement from work receiving position into work presenting relationship to said buttoning means 130

prior to the buttoning operation, means for effecting said movement automatically, and automatic means for discharging the work from the machine.

83. In a machine of the class described, work receiving means constructed and arranged to position the work in its initial presentation to the machine, and means for taking the work from the work receiving 10 means and performing a buttoning operation thereon.

84. In a buttoning machine, buttonhole fly receiving means, button receiving means, means for performing a buttoning operation 15 on the work, and operating mechanism for causing said buttoning means to take the work from the receiving means and to perform a buttoning operation thereon.

85. In a machine of the class described, 20 work receiving means and means for taking the work from the work receiving means and performing a buttoning operation thereon, together with means for discharging the buttoned work from the machine at the 25 conclusion of the buttoning operation.

86. In a machine of the class described, work receiving means constructed and arranged to position the work in its initial presentation to the machine, work holding 30 means arranged to take the work from the work receiving means, buttonhole fly engaging means, and mechanism for relatively moving said work holding means and buttonhole fly engaging means to effect a buttoning 35 operation.

87. In a machine of the class described, work receiving means, buttoning means including means for taking the work from the work receiving means and positioning it for 40 a buttoning operation, and mechanism for relatively operating said means to cause the work to be delivered to the work positioning means and a buttoning operation to be effected.

88. In a machine of the class described, buttonhole fly engaging means, work receiving means constructed and arranged to position the work in its initial presentation to the machine, means for taking the work 50 therefrom, and mechanism for relatively moving said buttonhole fly engaging means and said last named means to effect a buttoning operation.

89. In a machine of the class described, 55 buttonhole fly engaging means, button receiving means constructed and arranged to position a button in the initial presentation of the work to the machine, means for taking a button therefrom, and mechanism for relatively moving said last named means and said buttonhole fly engaging means to effect a buttoning operation.

90. In a buttoning machine, a buttoner, 60 button holding means, buttonhole fly receiving means, button receiving means, mecha-

nism for moving said receiving means to present the work to said buttoner and button holding means, and mechanism for relatively moving said buttoner and button holding means to cause the buttoner and the button holding means to take the work from said receiving means and to perform a buttoning operation thereon.

91. In a machine of the class described, buttonhole fly engaging means, work receiving means, work positioning and holding means, mechanism for relatively moving said receiving and positioning and holding means to position the work presented by the work receiving means, mechanism for 80 causing the positioning and holding means to engage and take the work from the receiving means, and mechanism for relatively moving the fly engaging means and work positioning and holding means to effect a 85 buttoning operation.

92. In a machine of the class described, work receiving means constructed and arranged to position the work in its initial presentation to the machine, means for taking the work from the receiving means and performing a buttoning operation with respect to the work, and mechanism for moving the receiving means to deliver the work 90 to the second named means.

93. In a machine of the class described, work receiving means constructed and arranged to position the work in its initial presentation to the machine, means for taking the work from the work receiving means 100 and performing a buttoning operation with respect to the work, and means for withdrawing said receiving means to an inoperative position prior to the buttoning operation.

94. In a machine of the class described, work receiving means constructed and arranged to position the work in its initial presentation to the machine, means for taking the work from the work receiving means 110 and performing a buttoning operation with respect to the work, and mechanism operating to move said receiving means to deliver the work to the second named means and thereafter to withdraw the receiving 115 means to an inoperative position.

95. In a buttoning machine, buttoning means, work receiving means mounted for movement from work receiving position into work presenting relationship to said buttoning means, mechanism for causing said buttoning means to take the work from the work receiving means, and mechanism for effecting said movement of the work receiving means and for moving the latter means into 120 an inoperative position with relation to the buttoning means after the work has been delivered to the buttoning means.

96. In a machine for performing a buttoning operation with respect to a button 130

- attached to a button piece, work receiving means constructed and arranged to position the work in its initial presentation to the machine, said work receiving means having 5 means for spreading a buttonhole, buttoning means, and mechanism for operating said means to cause the buttonhole to be spread and a buttoning operation to be effected.
- 10 97. In a buttoning machine, means for performing a buttoning operation with respect to a button attached to a button piece, work receiving means constructed and arranged to position the work in its initial 15 presentation to the machine and including parts arranged to open a buttonhole for the operation of the buttoning means, and mechanism for relatively moving said means to present the work for the buttoning operation.
- 15 98. In a machine for performing a buttoning operation with respect to a button attached to a button piece, work receiving means constructed and arranged to position 20 the work in its initial presentation to the machine and including means for entering and spreading a buttonhole, buttoning means, and mechanism for operating said means to cause the buttonhole to be spread and a buttoning operation to be effected.
- 25 99. In a buttoning machine, the combination with means for positioning a button attached to a button piece, of means constructed and arranged to engage a buttonhole fly simultaneously at opposite sides of a buttonhole opposite to the said button, and mechanism for operating said fly engaging means to cause said means to spread said buttonhole.
- 30 100. In a buttoning machine, buttoning means constructed and arranged to perform a buttoning operation with respect to a button attached to a button piece, means acting simultaneously upon the opposite sides of a buttonhole to spread the buttonhole to facilitate the action of the buttoning means, and operating mechanism for each of said means.
- 35 101. In a machine of the class described, work receiving means, buttoning means, mechanism for effecting relative movement of said means to present the work to the buttoning means, and means operated to spread a buttonhole during said relative movement of the work receiving means and buttoning means.
- 40 102. In a machine of the class described, work receiving means, means for spreading a buttonhole, buttoning means, and mechanism for moving said receiving means to present the work to the buttoning means, said mechanism including means operating to cause the buttonhole spreading means to spread the buttonhole during said movement of the work receiving means.
- 45 103. In a machine of the class described, work receiving means, means for taking the work from the receiving means and entering and positioning a buttonhole, and means for spreading the buttonhole to facilitate the entrance of the positioning means. 70
- 50 104. In a machine of the class described, means for entering a buttonhole and positioning a button, and means for spreading the buttonhole to facilitate the entrance therein of the first named means. 75
- 55 105. In a buttoning machine, means for performing a buttoning operation, means for moving a button into operative relationship to said means, buttonhole fly receiving means including devices arranged to open a buttonhole for the operation of the buttoning means, and means for moving said receiving means to present the fly to the buttoning means. 80
- 60 106. In a buttoning machine, work holding means, button receiving means, buttonhole fly receiving means including parts arranged to spread a buttonhole, both of said receiving means being movable from work receiving position into work presenting relationship to said work holding means, means for moving both of the said work receiving means into an inoperative position with relation to said work holding means after the work has been delivered thereto, and means 90 coöoperating with said holding means to effect a buttoning operation. 95
- 65 107. In a buttoning machine, work holding means, button receiving means, buttonhole fly receiving means including parts arranged to spread a buttonhole, both of said receiving means being movable from work receiving position into work presenting relationship to said work holding means, said work holding means including a device 100 arranged to enter the buttonhole while it is spread by said fly engaging means and to engage the button head and an anvil to support the button eye, and mechanism for moving said fly receiving means into an inoperative position with relation to said work holding means after the entrance of said device in the buttonhole and for moving said button receiving means into an inoperative position after holding engagement 105 of the holding means with the button has been effected. 110
- 70 108. In a buttoning machine, work holding means, buttonhole fly receiving means including means for spreading a buttonhole, said work holding means including a device arranged to enter the buttonhole while it is spread by said spreading means, mechanism for withdrawing said spreading means from the buttonhole after the entrance therein of said device, button receiving means, and mechanism for moving said button receiving means into position 115
- 75 120
- 80 125

to deliver a button to said holding means after the withdrawal of said spreading means and for continuing the movement of said button receiving means to an inoperative position after delivery of the button to said holding means.

109. In a machine of the class described, means designed to permit the presentation thereto of work provided with a plurality 10 of buttons and buttonholes and to perform a plurality of complete buttoning operations with respect to the said work, and mechanism for causing said means to perform said buttoning operations substantially simultaneously.

110. In a machine of the class described, means designed to permit the presentation thereto of a shoe upper provided with a plurality of buttons and buttonholes and 20 to effect relative movement of the button piece and buttonhole fly of said upper, and mechanism for operating said means in such a manner as to effect substantially simultaneously a plurality of complete buttoning 25 operations through said relative movement.

111. In a machine of the class described, buttoning means designed to permit the presentation thereto of work provided with a plurality of buttons and buttonholes and 30 to force a plurality of buttonholes over the heads of a plurality of opposed buttons to perform a complete buttoning operation with respect to each of said buttons, and mechanism arranged to operate the said 35 buttoning means in such manner as to effect the said buttoning operations substantially simultaneously.

112. In a machine of the class described, a plurality of sets of operating instrumentalities, each of said sets comprising means 40 for performing a complete buttoning operation, in combination with mechanism for operating the said sets simultaneously to cause a plurality of buttoning operations to 45 be effected at substantially the same time.

113. In a machine of the class described, a plurality of sets of operating instrumentalities, each of said sets comprising means 50 for performing a complete buttoning operation, in combination with mechanism arranged to operate the said means simultaneously in such manner as to cause a plurality of complete buttoning operations to 55 be effected at substantially the same time, and means operating to discharge the buttoned work from the machine.

114. In a buttoning machine, a plurality 60 of buttoning means, work receiving means, and mechanism for relatively moving said means to present the work to all of said buttoning means at substantially the same time and for causing said buttoning means to perform a plurality of complete buttoning operations substantially simultaneously.

115. In a buttoning machine, a plurality 65 of buttoning means, means for receiving the work and presenting it to said buttoning means, operating mechanism for causing said buttoning means to perform a plurality of complete buttoning operations on the 70 work substantially simultaneously, and means for discharging the work from the machine.

116. In a machine of the class described, a plurality of sets of operating instrumentalities, each of said sets comprising work receiving means and means for taking the work from the receiving means and performing a complete buttoning operation thereon, and mechanism arranged to operate the several sets in such a manner as to effect substantially simultaneously a plurality of complete buttoning operations.

117. In a machine of the class described, a plurality of sets of operating instrumentalities, each of said sets comprising relatively movable buttonhole fly engaging means and work positioning means, and mechanism for relatively moving the buttonhole fly engaging means and work positioning means of the several sets simultaneously to cause a plurality of complete buttoning operations to be performed at substantially the same time.

118. In a machine of the class described, a plurality of sets of operating instrumentalities, each of said sets comprising means for holding a button and positioning a buttonhole together with buttonhole fly engaging means, in combination with mechanism 100 for operating the several sets in such a manner as to cause a plurality of complete buttoning operations to be effected at substantially the same time.

119. In a machine of the class described, a plurality of sets of operating instrumentalities, each of said sets comprising means for engaging a button head and supporting a button eye together with buttonhole fly 110 engaging means, in combination with mechanism for operating the several sets in such a manner as to cause a plurality of buttoning operations to be effected substantially simultaneously.

120. In a machine of the class described, means for engaging the heads of a plurality 115 of buttons, means for supporting the eyes of said buttons, a plurality of buttoners, and mechanism for relatively moving said buttoners and said other means to effect substantially simultaneously a plurality of complete buttoning operations.

121. In a buttoning machine, a plurality 125 of sets of operating instrumentalities, each of said sets comprising button receiving means, buttonhole fly receiving means, a plunger, an anvil co-operating with the plunger to hold a button for a buttoning oper-

ation and buttonhole fly engaging means, together with mechanism for operating said sets in such a manner as to effect a plurality of complete buttoning operations at substantially the same time.

122. In a buttoning machine, buttoning means, work receiving means comprising a plurality of button receiving forks each opening outwardly away from the machine 10 to facilitate the introduction of buttons therein, and mechanism for thereafter relatively operating said buttoning means and said receiving means in such a manner as to effect buttoning operations with respect to 15 said buttons.

123. In a buttoning machine, buttoning means movable in a substantially vertical plane, a series of horizontally disposed supporting bars, a series of button receiving 20 forks carried at the outer ends of said bars, and mechanism for relatively operating said means and said forks to effect buttoning operations with respect to buttons received in said forks.

124. In a buttoning machine, a horizontal series of buttonhole fly supporting members having the fly supporting faces of said members disposed at elevations progressively increasing from the end members toward the 30 center of the series.

125. In a buttoning machine, a horizontal series of buttonhole fly supporting members, the members of said series increasing in thickness progressively from the end members toward the center of the series to present the fly supporting faces of adjacent members at progressively increasing elevations.

126. In a buttoning machine, in combination, a plurality of sets of instrumentalities, each of said sets comprising a work holding means and buttonhole fly engaging means coöperating with the holding means to perform a buttoning operation, said sets being 40 constructed and arranged so that the positional relationship between said sets may be varied while maintaining substantially unchanged the relationship between each work holding means and its coöperating fly engaging means, and operating mechanism for 45 said sets.

127. In a buttoning machine, in combination, a plurality of sets of instrumentalities, each of said sets comprising a work holding 55 means and a buttonhole fly engaging means coöperating with the holding means to perform a buttoning operation, adjusting means constructed to vary the positional relationship between said sets, and operating mechanism for said sets.

128. In a buttoning machine, a plurality of sets of instrumentalities, each of said sets comprising buttoning means and work receiving means, means for adjusting said sets

to vary the positional relationship of said sets while maintaining substantially unchanged the relation between each buttoning means and its coöperating work receiving means, and operating mechanism for said sets.

129. In a buttoning machine, in combination, a plurality of sets of buttoning instrumentalities, each of said sets comprising a buttonhole fly engaging means and a button holding means having parts supported independently of the buttonhole fly engaging means, means whereby the spacing of said instrumentalities may be varied while maintaining substantially unchanged the relationship between each fly engaging means 75 and its coöperating work holding means, and operating mechanism for said instrumentalities.

130. In a machine of the class described, a plurality of sets of operating instrumentalities, each of said sets having buttonhole fly engaging means, in combination with mechanism for simultaneously moving the said fly engaging means to adjust the said means according to the spacing of the buttonholes in the buttonhole fly to be operated upon.

131. In a machine of the class described, a plurality of sets of operating instrumentalities, each of said sets having buttonhole fly engaging means, in combination with means for moving the said means toward or from each other to position them according to the spacing of the buttonholes in the buttonhole fly to be operated upon.

132. In a machine of the class described, a plurality of sets of operating instrumentalities each comprising means for effecting a buttoning operation, a controller, connections from the controller to the several sets, 105 and mechanism for operating said controller to cause the said sets to be positioned upon movement of the controller according to the spacing of the buttons and buttonholes with respect to which the buttoning operations 110 are to be performed.

133. In a buttoning machine, a head, a plurality of buttoners, a plurality of buttoner supports mounted side by side in said head for movement toward or from each other, two series of oppositely extending toggle links, each of said links being pivotally connected to one of said supports, a common center link pivotally connected to each of said links and fulcrumed on the head, 115 120 and a controller for operating said toggles through said common link.

134. In a buttoning machine, a plurality of sets of operating instrumentalities, each of said sets comprising work holding means 125 and buttonhole fly engaging means coöperating with the said holding means to perform a buttoning operation, together with

means for adjusting said sets according to the spacing of the buttons and buttonholes to be operated upon, and a friction brake for maintaining said sets in adjusted position.

135. In a buttoning machine, a reciprocating head, a plurality of buttoners, a plurality of buttoner supports positioned side by side in said head, a lever fulcrumed on 10 said head and having link connections with said supports to adjust the spacing of said supports, and a controller having a connection with said lever permitting free movement of the lever relatively thereto in the 15 direction of movement of said head but operative to swing said lever about its fulcrum when moved in a direction transverse to the direction of movement of said head.

136. In a buttoning machine, a plurality 20 of buttoners mounted for adjustment toward or from each other, a plurality of work receiving members arranged to coöperate with said buttoners, a plurality of work holding devices associated with said buttoners, a controller, and connections from said controller to each of said instrumentalities arranged to cause said instrumentalities to be simultaneously adjusted upon movement of said controller according to the spacing of the 25 buttons and buttonholes to be operated upon.

137. In a buttoning machine, a plurality 30 of buttoners, a plurality of button head engaging devices, a plurality of associated button eye supporting members, a controller, and toggle connections therefrom to said instrumentalities arranged to cause said buttoners, devices and members to be simultaneously adjusted upon movement of said 35 controller to position the said instrumentalities according to the spacing of the buttons and buttonholes to be operated upon.

138. In a buttoning machine, a plurality 40 of guides movable toward or from each other, a plurality of supporting bars confined in said guides for movement therewith, work receiving means carried by each of said bars, a controller mounted for bodily sliding movement, and lever connections 45 from said controller to each of said guides constructed and arranged to move said guides simultaneously toward or from each other upon movement of said controller.

139. In a buttoning machine, a series of 50 guides movable toward or from each other, a plurality of supporting bars slidable through said guides and confined by the walls of said guides, work receiving means carried at the front ends of said bars, means 55 connected with the rear ends of said bars arranged to reciprocate said bars through said guides while permitting free movement of said bars with said guides upon movement of the guides toward or from each

other, a sliding controller, and toggles connecting said controller to each of said guides for moving the guides toward or from each other upon movement of the controller.

140. In a buttoning machine, a series of 60 button supports, a series of bars carrying said supports, a locking device common to all of said bars and arranged in one position of said device to lock said bars in the machine and in another position to unlock said bars to permit removal of said bars from the 65 machine, and means for locking said locking device in locking position.

141. In a buttoning machine, a plurality of 70 sets of operating instrumentalities, each of said sets comprising buttonhole fly engaging means and operating mechanism therefor, said fly engaging means being mounted for adjustment according to the angular positions of the buttonholes in the work to be operated upon.

142. In a buttoning machine, a plurality 75 of sets of operating instrumentalities, each of said sets comprising buttonhole fly engaging means, operating mechanism therefor, and means for independently adjusting 80 said fly engaging means according to the angular positions of the buttonholes in the work to be operated upon.

143. In a buttoning machine, a plurality 85 of sets of operating instrumentalities, each of said sets comprising buttonhole fly engaging means and buttonhole engaging and positioning means, and means for adjusting said fly engaging means and said buttonhole 90 engaging and positioning means according 100 to the angular positions of the buttonholes in the work to be operated upon.

144. In a buttoning machine, a plurality 95 of sets of operating instrumentalities designed to permit the presentation thereto of 105 work provided with a plurality of buttons and buttonholes, each of said sets comprising buttonhole fly engaging means and means for positioning a button and buttonhole, operating mechanism therefor, and 110 means for adjusting the buttonhole fly engaging means and positioning means of each set according to the angular positions of the buttonholes in the work to be operated upon.

145. In a buttoning machine, a plurality 115 of sets of operating instrumentalities, each of said sets comprising buttonhole fly engaging means, and operating mechanism therefor, said fly engaging means being mounted for adjustment to position the said 120 means according to the curve upon which the buttonholes are set in the work to be operated upon.

146. In a buttoning machine, a plurality 125 of sets of operating instrumentalities, each of said sets comprising buttonhole fly engaging means, and operating mechanism therefor, said fly engaging means being inde-

pendently adjustable to position them according to the curve upon which the buttonholes are set in the work to be operated upon.

5 147. In a buttoning machine, a plurality of sets of operating instrumentalities, each of said sets comprising a buttoner and buttonhole engaging and positioning means, said buttoners and buttonhole positioning 10 means being adjustable to position them according to the line of the buttonholes in the work to be operated upon, and operating mechanism for said sets.

148. In a buttoning machine, a plurality 15 of sets of operating instrumentalities designed to permit the presentation thereto of work provided with a plurality of buttons and buttonholes, each of said sets comprising buttonhole fly engaging means and means 20 for positioning a button and buttonhole, and operating mechanism therefor, the buttonhole fly engaging means and positioning means of each set being adjustable to position them according to the line upon which 25 the buttonholes are set in the work to be operated upon.

149. In a buttoning machine, a plurality 30 of sets of buttoning instrumentalities, each of said sets comprising means for engaging a buttonhole fly and for positioning a buttonhole, a common support for said means, said sets being constructed and arranged so that said means may be adjusted relatively to said support to correspond to the line of 35 buttonholes in the buttonhole fly and to the spacing of said buttonholes, and mechanism operating through said support to move said means simultaneously to effect a plurality of complete buttoning operations.

40 150. In a buttoning machine, a plurality of sets of buttoning instrumentalities, each of said sets constructed to perform a complete buttoning operation, and means for causing said sets to operate substantially simultaneously upon the work, said instrumentalities being constructed and arranged 45 to be adjustable to position them for differently spaced buttonholes, for buttonholes set in different angular positions, and according 50 to the line or curve of the buttonholes in the work to be operated upon.

151. In a machine of the class described, buttoning means, and mechanism for operating said means in such a manner as to 55 cause the said means to effect a buttoning operation, said mechanism operating at the conclusion of the buttoning operation to restore the parts to their initial positions and including means for automatically stopping 60 the machine when the parts have been so restored to their initial positions.

152. In a machine of the class described, 65 means for performing a plurality of complete buttoning operations at one operation of the machine, and operating mechanism

for said means including means for preventing the machine from repeating.

153. In a machine of the class described, means designed to permit the presentation thereto of work provided with a plurality 70 of buttons and buttonholes and to perform at one operation of the machine a plurality of complete buttoning operations with respect to the said work, and operating mechanism for said means including means for preventing the machine from operating more than once at a single actuation of the machine.

154. In a buttoning machine, means for holding a button constructed and arranged 80 to position a buttonhole also, buttonhole fly engaging means for engaging the edge binding stitches of the buttonhole, and mechanism for relatively moving said means to effect a buttoning operation.

155. In a buttoning machine, a plunger and an anvil coöoperating to hold a button and position a buttonhole, tuckers for engaging the edge binding stitches upon opposite sides of the buttonhole, and mechanism for relatively moving said instrumentalities to effect a buttoning operation.

156. In a buttoning machine, a plunger, an anvil coöoperating therewith, a buttoner, and mechanism for relatively moving said 95 instrumentalities to effect a buttoning operation.

157. In a buttoning machine, means for holding a button constructed and arranged 100 to position a buttonhole in alignment with the head of the button, buttonhole fly engaging means in alignment with the head of the button, and mechanism for relatively moving said means to effect a buttoning operation.

158. In a buttoning machine, means for entering a buttonhole and engaging the head of a button, means for supporting the eye of the button, tuckers adjacent to said first named means on opposite sides thereof, and mechanism for relatively moving said means and said tuckers to cause said tuckers to engage the buttonhole fly directly above the head of the button and to cause a passage of the button through the buttonhole.

159. In a machine of the class described, buttonhole fly engaging means, work holding means including a spring arranged to yield under pressure of the work, a heavier spring for subsequently increasing the pressure of the holding means upon the work, and mechanism for relatively moving said fly engaging means and said holding means to effect a buttoning operation.

160. In a machine of the class described, buttonhole fly engaging means, work holding means including a spring arranged to yield under pressure of the work to position the work holding means according to 130

the contour and thickness of the button head, and mechanism for relatively moving said fly engaging means and said holding means to cause a holding engagement of the holding means with the work and a buttoning operation to be effected.

161. In a machine of the class described, buttonhole fly engaging means, work holding means comprising means for engaging the head of a button and means for supporting the eye of the button, said button head engaging means including a spring arranged to yield under pressure of the work to position the button head engaging means according to the contour and thickness of the button head and a heavier spring for subsequently increasing the pressure of the button engaging means against the button, and mechanism for relatively moving said fly engaging means and said holding means to cause a holding engagement of the holding means with the work and a buttoning operation to be effected.

162. In a buttoning machine, a buttoner comprising means for engaging the fly at the side edges of a buttonhole and additional means arranged to engage the fly adjacent to the buttonhole in advance of the first named means, and operating mechanism for said means.

163. In a buttoning machine, button holding means including means arranged to enter a buttonhole and engage the head of a button, buttonhole fly engaging means comprising means arranged to engage the stock adjacent to a buttonhole to push the said stock into engagement with the head of the button held by said holding means, and means operating upon engagement of the said stock with the button head to force the edges of the buttonhole over the head of the button to complete the buttoning operation.

164. In a buttoning machine, button holding means including means arranged to enter a buttonhole and engage the head of a button, buttonhole fly engaging means comprising means for engaging the fly adjacent to a buttonhole and upon the sides thereof and additional means for engaging the stock at the front and rear of the buttonhole and forcing the said stock into engagement with the head of the button in advance of the action of the first named fly engaging means, and mechanism for thereafter relatively moving the button holding means and fly engaging means to effect a buttoning operation.

165. In a buttoning machine, button holding means including means arranged to enter a buttonhole and engage the head of a button, buttonhole fly engaging means comprising a pair of tuckers for engaging the edges of a buttonhole and a pair of co-operating fingers arranged to engage and carry the stock ad-

jacent to the said buttonhole against the head of the button held by said holding means to position the stock for the operation of said tuckers, said fingers having out-turned ends shaped to prevent the said stock from puckering or wrinkling as it is carried against the head of the button, and operating mechanism for relatively moving said button holding and fly engaging means to effect a buttoning operation.

166. In a buttoning machine, means for positioning a buttonhole and holding a button, means for pushing the stock adjacent to the buttonhole against the head of the button, and means operating during the pushing action of said means to carry the edges of the buttonhole over the edge of the button head to complete the buttoning operation.

167. In a buttoning machine, means for holding the work for a buttoning operation, buttoning instrumentalities comprising tuckers and co-operating front and rear fingers, and mechanism for relatively moving the holding means and buttoning instrumentalities to effect a buttoning operation.

168. In a buttoning machine, means for holding a button for a buttoning operation including members arranged to enter and position a buttonhole and engage the head of the button, means for spreading said members apart while they are positioned in the buttonhole, and means for engaging the stock at the edges of the buttonhole and stripping the said stock off the said members and carrying it over the edge of the button head to effect a buttoning operation.

169. In a buttoning machine, means for holding a button for a buttoning operation including plungers arranged to enter and position a buttonhole and engage the head of a button, means for spreading said plungers apart while they are positioned in the buttonhole, and means arranged to be spread apart by the spreading movement of the plungers and operating to strip the stock at the edges of the buttonhole off said plungers and carry the said stock over the edge of the button head to effect a buttoning operation.

170. In a buttoning machine, means for holding a button for a buttoning operation including plungers arranged to enter and position a buttonhole and engage the head of the button, means operating to push the stock adjacent to the buttonhole against the head of the button, tuckers overlapping the plungers in contact with the outer sides thereof, means for spreading the plungers apart while they are positioned in the buttonhole, said means operating through the plungers to spread the tuckers apart, and mechanism for operating the tuckers to strip the stock adjacent to the edges of the buttonhole off the plungers and carry it under

the head of the button to complete the buttoning operation.

171. In a buttoning machine, an anvil for supporting the eye of a button, a plunger for engaging the head of a button, additional means for engaging the head of the button, buttonhole fly engaging means, and mechanism for relatively moving said button engaging means and said fly engaging means to effect a buttoning operation.

172. In a buttoning machine, an anvil for supporting the eye of a button, members for engaging the head of the button, a plunger between said members arranged to engage the head of the button held between said members and said anvil, buttonhole fly engaging means, and mechanism for relatively moving said button engaging instrumentalities and said fly engaging means to effect a buttoning operation.

173. In a buttoning machine, members for engaging the head of a button, said members having their button engaging faces shaped to conform substantially to the contour of the crown of the button head and spaced for engagement with the button on opposite sides of the center of the head.

174. In a buttoning machine, members for engaging the head of a button, said members having their button engaging faces curved in conformity to the contour of the button head in planes extending substantially at right angles to each other, said faces being spaced for engagement with the button on opposite sides of the center of the head.

175. In a buttoning machine, button head engaging members positioned side by side and provided with inclined surfaces upon their adjacent faces, a button head engaging plunger between said members, and means for effecting relative movement between said plunger and said members to cause said plunger by wedging engagement with said inclined surfaces to spread said members apart.

176. In a buttoning machine, a plunger having a slot therein, a block in said slot, spring plungers fastened at their upper ends to opposite sides of said block, and a spring operating normally to hold said block at one end of said slot, said plunger and said spring plungers having coöperating faces formed to cause said spring plungers to be wedged apart upon movement of said block from its normal position in said slot.

177. In a buttoning machine, a supporting sleeve, buttoning instrumentalities carried by said sleeve for movement therewith, a spring pressed plunger movable in said sleeve, and means for relatively moving said sleeve and said plunger.

178. In a buttoning machine, a supporting sleeve, opposed buttoning fingers and opposed tuckers depending from said

sleeve, a plunger slidably mounted in said sleeve, a spring interposed between said plunger and said sleeve, spring plungers carried by said plunger and movable lengthwise of the plunger, and a second spring interposed between said plunger and said spring plungers.

179. In a buttoning machine, a supporting sleeve, a button head engaging plunger movable in said sleeve and normally in a predetermined position therein, means for supporting the eye of the button, and adjustable means for determining said predetermined position of the plunger to accommodate the plunger to button heads of different thicknesses.

180. In a button machine, a supporting sleeve, opposed tuckers depending therefrom, and button engaging means carried in said sleeve, said tuckers being mounted for adjustment toward and from a button engaged by said means.

181. In a buttoning machine, a holder, a sleeve in said holder, button head engaging means in said sleeve, buttoning instrumentalities carried thereby, said sleeve being mounted for turning movement in said holder to cause said means and said instrumentalities to be adjusted according to the angular position of the buttonhole with respect to which a buttoning operation is to be performed, and means for holding said sleeve in adjusted position.

182. In a buttoning machine, a holder, a sleeve in said holder, and buttoning instrumentalities carried by said sleeve, said sleeve being mounted for adjustment to position said instrumentalities according to the angular position of the buttonhole with respect to which a buttoning operation is to be performed.

183. In a buttoning machine, work holding means comprising a plurality of opposed devices movable to exert pressure against the head and eye of a button to sustain the button between them, and means for presenting a button in position to be clamped by said devices.

184. In a buttoning machine, button supports comprising a member constructed and arranged for movement into engagement with the crown of a button head, and a member movable into position to support the eye of the button in opposition to said member.

185. In a buttoning machine, button holding means comprising a member movable into engagement with the head of a button and a member for exerting pressure against the eye of the button in opposition to said first-named member.

186. In a buttoning machine, coöperating button supports comprising a button head engaging member shaped to conform substantially to the contour of the button head.

- and a button eye supporting member provided with a flat work engaging face, buttonhole fly engaging means, and mechanism for relatively moving said supports and said means to effect a buttoning operation.
- 5 187. In a buttoning machine, coöperating work supports including an anvil, a supporting bar for said anvil, an ejector mounted for sliding movement along said bar, and means for operating said ejector to discharge the work from the machine when permitted by said work supports.
- 10 188. In a buttoning machine, coöperating work supports including an anvil, a supporting bar for said anvil, an ejector, a lever for operating said bar, and a connection from said lever to said ejector arranged to be actuated to operate the ejector at predetermined times only during the movement of said lever.
- 15 189. In a buttoning machine, button receiving means, and a button piece supporting spring adjacent to said means and positioned to guide the button piece to facilitate the introduction of a button into the receiving means.
- 20 190. In a buttoning machine, means for holding a button, button receiving means, and a button piece supporting spring carried by said holding means and shaped at its free end to prevent catching in the work during its introduction into the machine.
- 25 191. In a buttoning machine, button receiving means comprising members relatively movable to receive the eye of a button between them and a fork to receive the head of the button.
- 30 192. In a buttoning machine, buttoning means, work receiving means comprising a fork constructed and arranged to prevent disengagement of the work from the fork during presentation of the work for the operation of the machine, and means for effecting relative movement of the work receiving means and the buttoning means to present the work to the buttoning means.
- 35 193. In a buttoning machine, buttoning means, button receiving means comprising a receiving fork and means for holding a button in the fork for presentation of the button for the operation of the machine, and means for relatively moving the buttoning means and the button receiving means to effect said presentation of the button.
- 40 194. In a buttoning machine, buttoning means, work receiving means having provision for preventing disengagement of the work from the receiving means during presentation of the work to the buttoning means, and means for effecting a relative movement of the work and the buttoning means to present the work to the buttoning means.
- 45 195. In a buttoning machine, buttoning means and button receiving means independ-
- ent of the buttoning means and constructed and arranged to present a button to the buttoning means in a predetermined position only, said receiving means being constructed and arranged to position the button in the initial presentation of the work to the machine.
- 50 196. In a buttoning machine, buttoning means and means for receiving in an upright position a button attached to a button piece and holding the button in said position for delivery to the buttoning means, said receiving means being constructed and arranged to position the button in the initial presentation of the work to the machine.
- 55 197. In a buttoning machine, means for receiving a button comprising a receiving fork and spring fingers arranged to engage the eye of the button to prevent accidental disengagement of the button from the fork.
- 60 198. In a buttoning machine, means for receiving a button comprising a button sustaining fork constructed and arranged to leave the crown of the button head free and to limit movement of the button in said means transversely thereof by engagement with the periphery of the button head on opposite sides of said head.
- 65 199. In a buttoning machine, button receiving means comprising a guide fork arranged to sustain the head of a button, spring fingers below said fork arranged to receive the eye of the button between them, and an upper fork arranged to engage the periphery of the button head upon opposite sides thereof.
- 70 200. In a buttoning machine, movable work receiving means, coöperating work supports movable in a plane substantially perpendicular to the plane of movement of the receiving means and comprising an upper member above said receiving means and a lower member below the receiving means, mechanism for moving said receiving means from a work receiving position out of alignment with said supports to a position to deliver the work to said supports and for continuing the movement of the receiving means to an inoperative position after delivery of the work to said supports, and mechanism for operating said supports to cause them to take the work from the receiving means.
- 75 201. In a buttoning machine, means for entering and spreading a buttonhole, and mechanism for lowering said means out of the buttonhole at a predetermined time in the operation of the machine.
- 80 202. In a buttoning machine, work holding means including means for entering and positioning a buttonhole, together with work receiving means including means for entering and spreading the buttonhole.
- 85 203. In a buttoning machine, work holding means including means for entering

- and positioning a buttonhole, work receiving means including means for entering and spreading the buttonhole, mechanism for relatively moving said means to cause said entering and positioning means to enter the 5 buttonhole, and mechanism for lowering said spreading means out of the buttonhole after the entrance therein of the entering and positioning means.
- 10 204. In a buttoning machine, means for supporting a buttonhole fly adjacent to a buttonhole, a pair of buttonhole spreaders for entering and spreading the said buttonhole, said spreaders being mounted for movement about a pivot carried by said first named means, together with means for swinging said spreaders about said pivot to withdraw the spreaders from the buttonhole.
- 15 205. In a buttoning machine, means for supporting a buttonhole fly adjacent to a buttonhole, a pair of buttonhole spreaders for entering and spreading the said buttonhole, said spreaders being mounted for movement about a pivot carried by said first named means, together with means operating normally to maintain said spreaders in operative position, and means for moving said spreaders out of operative position.
- 20 206. In a buttoning machine, a buttonhole fly supporting fork, a bar carrying said fork, a pair of spreaders below said bar and having blades projecting upwardly through said fork, a support for said spreaders pivotally connected to said bar, and 25 mechanism for swinging said spreaders about their pivotal connection with said support.
- 25 207. In a buttoning machine, an upper member, buttonhole fly receiving means carried thereby, buttonhole spreaders, a support for said spreaders mounted to swing about a pivot carried by said upper member, a lower member, coöperating inclined faces on said support and said lower member, and mechanism for relatively moving said members to cause said support and said spreaders to be swung about said pivot through sliding engagement of said inclined faces.
- 30 208. In a buttoning machine, a pair of buttonhole spreaders, a support for the spreaders to which said spreaders are pivotally connected for opening and shutting movement, means operating normally to keep said spreaders together, a member adjacent to said spreaders, and mechanism for relatively moving said support and said member, said spreaders having a slot formed by recesses in their adjacent faces and said 35 member having a projection therefrom arranged to stand in said slot and to operate during relative movement of said support and said member to wedge said spreaders apart.
- 35 209. In a buttoning machine, coöperating work supports comprising a plunger and an opposed anvil, said plunger and said anvil being constructed and arranged to be adjusted out or in, from or toward the machine. 70
210. In a buttoning machine, work receiving means, and work holding means co-operating with said receiving means, both said means being adjustable out or in, from or toward the machine. 75
211. In a buttoning machine, button receiving means, buttonhole fly receiving means, and work holding means coöperating with said button and buttonhole fly receiving means and comprising a plunger and 80 an opposed anvil, each of said means and said plunger and said anvil being adjustable out or in, from or toward the machine. 80
212. In a buttoning machine, buttonhole fly engaging instrumentalities and means 85 for supporting said instrumentalities, said means being mounted for swinging movement to adjust said instrumentalities out or in, toward or from the machine for the purpose described. 90
213. In a buttoning machine, work receiving means, a supporting bar therefor, and a movable frame for operating said bar, said bar being secured to said frame for adjustment lengthwise of said bar. 95
214. A buttoning machine having, in combination, button positioning means, buttonhole fly engaging means having portions shaped for engagement with the fly at the front and the rear of a buttonhole, and 100 mechanism for relatively moving said means to effect a buttoning operation.
215. A buttoning machine having, in combination, button positioning means, buttonhole fly engaging means comprising members for engaging the fly at the ends of a buttonhole, and mechanism constructed and arranged to move said fly engaging means into engagement with the buttonhole fly and to effect relative movement of said button positioning and buttonhole fly engaging means to perform a buttoning operation. 105
216. A buttoning machine having, in combination, button positioning means, and tuckers constructed and arranged to dispose 110 the material of a buttonhole fly smoothly in buttoned position under the edge of the head of the button. 115
217. A buttoning machine having, in combination, button positioning means, and buttonhole fly engaging means comprising tuckers for pressing the material of the buttonhole fly over the head of the button, said tuckers being constructed and arranged for inward movement toward the eye of the button to dispose the material smoothly under the button head. 120
218. A buttoning machine having, in combination, button positioning means, tuckers for engaging the material of a buttonhole 125
219. A buttoning machine having, in combination, button positioning means, tuckers for engaging the material of a buttonhole 130

- fly at opposite sides of a buttonhole, and means for operating said tuckers to carry the material of said fly over the head of the button, said tuckers being movable also inwardly under the button head to dispose the material of the buttonhole fly smoothly in buttoned position.
219. A buttoning machine having, in combination, means for engaging a button piece in a position opposite to the eye of a button, buttonhole fly engaging means, and mechanism for effecting relative movement of said means to perform a buttoning operation.
220. A buttoning machine having, in combination, means arranged to be positioned under the eye of a button to support the button, means for engaging a buttonhole fly, and mechanism for effecting relative movement of said means to perform a buttoning operation.
221. A buttoning machine having, in combination, means arranged to be positioned under the eye of a button to support the button in a substantially upright position in such manner as to leave free the sides and the bottom of the button head, buttonhole fly engaging means, and mechanism for effecting relative movement of said means to cause the material of the buttonhole fly at the edges of a buttonhole to be disposed under the head of the button.
222. A buttoning machine having, in combination, means arranged to be positioned under the eye of a button to support the button, means for engaging a buttonhole fly at the edges of a buttonhole positioned over the head of the button, and mechanism for operating said fly engaging means to cause said means to depress the material of the fly and dispose it under the button head.
223. In a machine of the class described, buttonhole fly engaging means, means for holding a button attached to a button piece, and operating mechanism constructed and arranged to move said button holding means into position to engage the head of the button and thereafter to effect relative movement of said button holding and fly engaging means in such manner as to effect a buttoning operation.
224. A machine of the class described having, in combination, means for supporting simultaneously a plurality of buttons attached in a row to a button piece, and means for effecting relative movements of said buttons and a buttonhole fly to perform buttoning operations with respect to said buttons without causing substantial movement of the button piece longitudinally of the row of buttons.
225. A machine of the class described having, in combination, means for positioning a button piece and a buttonhole fly with the corresponding buttons and buttonholes in opposed relation, and means for effecting relative movements of said buttons and buttonhole fly to perform substantially simultaneously a plurality of buttoning operations with respect to said buttons and buttonholes.
226. A machine of the class described having, in combination, means for positioning a buttonhole fly and a button piece with a row of buttonholes opposite to a row of buttons, and means for effecting relative movements of said buttons and buttonhole fly to perform buttoning operations with respect to said buttons without substantial movement of the work longitudinally of the rows of buttons and buttonholes.
227. A buttoning machine having, in combination, a plurality of sets of operating instrumentalities, each comprising a button receiving and positioning fork and buttonhole fly engaging means, and operating mechanism constructed and arranged to effect relative movement of the button receiving fork and the buttonhole fly engaging means of each set to cause a plurality of buttoning operations to be performed.
228. A buttoning machine having, in combination, means for engaging a buttonhole fly to position said fly when the work is initially presented to the machine, means for performing a buttoning operation on the work, and means for withdrawing said fly positioning means to an inoperative position before the buttoning operation is performed.
229. A buttoning machine having, in combination, work receiving means including a device arranged to project within a buttonhole to position the buttonhole fly when the work is presented to the machine, means for performing a buttoning operation on the work, and means for withdrawing said positioning device from the buttonhole before said buttoning operation is performed.
230. A buttoning machine having, in combination, means for engaging a buttonhole fly to position said fly when the work is initially presented to the machine, other means for engaging the fly to position it for the buttoning operation, and means for withdrawing said first named positioning means upon the engagement of said other means with the fly.
231. A buttoning machine having, in combination, work receiving means including a device arranged to project within a buttonhole to position the buttonhole fly when the work is presented to the machine, other means for engaging the fly to position it for the buttoning operation, and means for withdrawing said first named positioning means from the buttonhole upon the engagement of said other means with the fly.
232. In a buttoning machine, work receiving means constructed and arranged to position a button piece and a buttonhole fly

when the work is initially presented to the machine, said means comprising a button receiving member and a device arranged to project within a buttonhole to position the buttonhole with respect to said member.

233. In a buttoning machine, work receiving means constructed and arranged to position a button piece and a buttonhole fly when the work is initially presented to the machine, said means comprising a button receiving fork and a device at the rear of said fork constructed to project within a buttonhole to position the buttonhole over the button in said fork.

15 234. In a buttoning machine, work receiving means constructed and arranged to position a button piece when the work is initially presented to the machine, said means having a button positioning opening arranged to extend in transverse relation to the longitudinal edge of the button piece.

25 235. In a buttoning machine, work receiving means constructed and arranged to position a button piece and a buttonhole fly when the work is initially presented to the machine, said means comprising a plurality of button receiving members and a plurality of buttonhole fly positioning devices constructed and arranged to project within the buttonholes to position the buttonholes with respect to the corresponding buttons.

35 236. A buttoning machine having, in combination, means for positioning a button, a pair of buttonhole fly engaging members arranged to engage the fly at opposite sides of a buttonhole corresponding to said button, means for moving said members toward the button to perform a buttoning operation, and means for imparting a separating movement to said members during their movement toward the button.

40 237. A buttoning machine having, in combination, means for positioning a button, a pair of buttonhole fly engaging members arranged to engage the fly at opposite sides

of a buttonhole corresponding to said button, means for effecting relative movement of said button positioning means and fly engaging members to perform a buttoning operation, and means operative upon said relative movement to effect a separating movement of the fly engaging members.

55 238. A buttoning machine having, in combination, buttoning means, and means for imparting to the work a positioning movement in a direction transverse to the longitudinal edge of the work to bring the work into position to be operated upon by the buttoning means.

60 239. A buttoning machine having, in combination, buttoning means, work receiving means, and means for operating the work receiving means to impart to the work a positioning movement in a direction transverse to the longitudinal edge of the work to bring the work into position to be operated upon by the buttoning means, said work receiving means including fingers oppositely disposed for engaging and retaining the work between them.

70 240. A buttoning machine having, in combination, buttoning members, a button head engaging member, a button piece engaging member for supporting the eye of a button, said last named member being arranged to hold the button against the pressure of the buttoning members, and means for effecting relative movement of said button head engaging member and button eye supporting member into operative relationship to a button and for then effecting relative movement of said buttoning members and the other members to perform a buttoning operation.

75 In testimony whereof I have signed my name to this specification in the presence of two subscribing witnesses.

HERBERT E. ENSLIN.
